UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TESTING DEVICE FOR TELEPHONE-EXCHANGE SYSTEMS.

Application filed May 8, 1923. Serial No. 637,417.

To all whom it may concern:

Be it known that I, ERIC R. LUNDIUS, a citizen of United States of America, residing at Brooklyn, in the county of Kings, State of New York, have invented certain new and useful Improvements in Testing Devices for Telephone-Exchange Systems, of which the following is a full, clear, concise, and exact description.

10 This invention relates to telephone exchange systems, and more particularly to a testing device for use in such a telephone system of the machine switching type.

15 In the operation of the telephone exchange system it is important to maintain a high standard of operating efficiency in the circuit paths over which the subscriber has access to responsive means in said exchange.

20 In some systems of the machine switching type non-numerical line switches are used to extend the calling subscribers' lines to the selective switches in the exchange. If the line and line switching apparatus are not in proper operating condition to test and 25 seize an idle selector switch the subscriber will be prevented from making calls.

25 The apparatus used in the line switching mechanism of a machine switching office is made up of moving parts subject to loss of 30 adjustment which may result from normal usage of the equipment. This loss of adjustment would result in improper functioning of the apparatus or failure to function.

35 There are, also, well known troubles encountered in the maintenance of line conductors extending from the switching mechanism to the subscriber's station.

40 Such failures would ordinarily cause the isolation of a subscriber. It is, therefore, important that equipment of this nature be regularly tested to determine, prior to its reported failure, whether it is in suitable condition for rendering efficient service.

45 It is the object of this invention to provide a device to make tests of the line circuit paths and line switching mechanism of a telephone exchange system.

50 The disclosure shows the invention applied to a testing device arranged for testing lines and line switching apparatus of the type disclosed in Patent No. 1,395,977 issued Nov. 1, 1921, to F. A. Stearn et al. It will be, however, apparent from the fol-

lowing description that the invention has a wide utility and that by slight modification it may be adapted to testing many other types of line switching mechanism and lines.

55 A feature of the invention resides in the seizure and control of a final selector switch by the testing circuit to function as a part 60 of the testing circuit by selecting the line or line switch apparatus to be tested. This final selector switch, when not connected to the testing circuit, forms a part of the exchange switching equipment for completing 65 calls in regular service.

A further feature of the invention relates 70 to accurately testing the adjustments of the relays of the line switch circuit on a regulated current flow basis. A step-by-step selector of the type well known in the art is 75 employed to successively associate the apparatus to be tested with the test circuit. Lamps are successively lighted to indicate the particular test being made and the success 75 of preceding tests.

80 A further feature of the invention relates to the operation of the line switch as in regular service to associate a district and sender selector with the testing circuit. The district and sender selector will function in this test, by transmitting dial tone through the selector contacts and contacts of the line switch circuit relays, to a receiver in the testing circuit. This tone is used as a successful test signal.

85 A further feature of the invention relates to the ability of the testing circuit to differentiate between a line switch circuit extending directly to a subscriber's station and a line switch circuit extending to a private branch exchange, together with the ability 90 to apply the proper test in accordance with this differentiation.

95 A further feature of this invention will be found in the making of ballistic tests successively on the tip and ring conductors of the line by the single actuation of a key in combination with a step-by-step selector of a well known type. Immediately preceding 100 each of the two successive ballistic tests any latent capacity in the conductors of the line, or electrically responsive apparatus connected to these conductors is discharged to prevent actuation of the responsive apparatus 105 when the ballistic test is applied.

— A further feature of the invention relates to the employment of a potentiometer to discharge latent capacity in a line, or responsive mechanism connected thereto, preceding a test of one of the line conductors, to prevent actuation of the responsive mechanism.

10 A further feature of the invention relates to the use of a meter for determining line conditions together with an automatic feature arranged to stop automatic progression for a limited time during each line test to facilitate the reading of the meter.

15 These and other features of the invention will be apparent from the following description taken in connection with the accompanying drawings in which Figs. 1, 2, 3, 4 and 5 form the testing circuit proper; Fig. 6 shows a final selector circuit used as an adjunct to the testing circuit; and Fig. 20 7 shows a line and line switch circuit, apparatus of a district and sender selector with which it is associated in service. Fig. 8 is a diagram showing the order in which the drawings should be arranged.

25 Fig. 1 shows the control apparatus for causing the final selector, Fig. 6, to select the line to be tested, also the key control for advancing the final selector, Fig. 6, in single steps.

30 Fig. 2 in combination with Fig. 3 shows the testing device for testing the line switch apparatus.

35 Fig. 4 shows a circuit for automatic discharge of latent capacity of the line in connection with a ballistic test of each side of the line.

40 Fig. 5 shows the controlling means for making an insulation breakdown test.

45 Fig. 6 shows a final selector switch which has access to the lines and line switch circuits to be tested. This final selector circuit is specially designed with jacks connected in such a manner that it may be used for test purposes when the patching cord and plugs associated with the testing equipment are inserted in said jacks. The leads of this final selector circuit are connected to the jacks in such a manner that when it is not in use as an adjunct to the testing circuit equipment it may be employed as a part of the machine switching apparatus for service connections.

55 The left hand part of Fig. 7 shows a line and line switch apparatus to be tested. A subscriber's station and a private branch exchange are shown optionally connected to the line. When the subscriber's station is connected to the line, conductor 783 is connected to arc 723 and conductor 764 is connected to conductor 715. When the private branch exchange is connected to the line conductor 783 is replaced by conductor 781 and conductor 764 is replaced by 763. A 60 district selector is diagrammatically illustrated in the upper right hand part of this

figure. Also a sender selector is diagrammatically illustrated in the lower left-hand part of this figure.

Description of apparatus.

70 The testing device disclosed in Figs. 1 to 5 inclusive, is enclosed in a portable box mounted on wheels, so that it may be easily moved among the switch frames in a switching room of the office, and is provided with 75 suitable jacks 320, 321, 322, 323 and 324 shown in Fig. 3, for connection, respectively, to the final selector circuit, insulation breakdown test battery, ballistic test battery and an interrupter.

80 In actual practice power is transmitted to the testing device through jacks on the testing device which are attached by other circuits to suitable power jacks on the selector switch frame. Such power connections include current supply for 48 volt direct current to the relays and step-by-step switches, and alternating current to apparatus on Figs. 4 and 5. For convenience of illustration, however, these jacks have been 85 omitted and the source of current and ground potential have been shown directly associated to the different pieces of apparatus.

90 Keys 120 to 129 shown in Fig. 1 are of the well known mechanically locked and electrically released type.

95 The step-by-step selectors shown in Figs. 2, 4 and 5 may be of any well known type, and are arranged to start at normal for each test.

100 Fig. 3 illustrates rheostats of the well known type numbered 350 to 357, inclusive. These rheostats are used in combination with milliammeter 302 for regulating the current flow in accordance with the voltage reading of the battery at the time that the tests are being made. This current flow regulation allows very accurate testing of 105 the non-operate and operate adjustments of 110 the line switch relays 701 and 702.

115 Meter 450 shown in Fig. 4 is for use both as a voltmeter and as a milliammeter. The milliammeter tap is shown between resistances 433 and 434, and is used for observation of line conditions when making ballistic and insulation breakdown tests.

120 The automatic final selector switch shown in Fig. 6, is of the well known power-driven type, in which a plurality of sets of brushes are mounted on a vertical brush shaft arranged to be selectively tripped into engagement with their individual sections of the panel terminal bank. The brush shafts are propelled in a vertical direction by means of 125 constantly rotating power drums. In general construction and operation, this switch is of the same character as the one shown and described in detail in the patent to E. B. Craft and J. N. Reynolds 1,123,696, issued 130

January 5, 1915. More specifically, the circuits of the final selector shown in Fig. 6 are described in the application of Alben E. Lundell, Serial No. 487,520, filed January 5, 1921.

The district and sender selectors, shown diagrammatically in Fig. 7 are of the same type also specifically described in application, Serial No. 487,520, filed July 25, 1921.

Having now described in a general way the apparatus employed in conducting tests and the manner in which it is to be used, it is thought that the invention will be better understood from a consideration of the general manner in which the testing will be conducted.

General description.

Assuming that a test is to be made of a certain line switch and line, the portable testing circuit will be taken to a point accessible to frame jacks such as 332 and 333 associated with a final selector circuit that will have access to the line to be tested. Patching cords such as 325 and 326 will be inserted in jacks 332, 333 and 320 and 321. The voltage of the office battery will then be noted and the rheostats adjusted to the proper value for the various tests. One of the locking keys 120 to 129 will be depressed to act as a start key and cause brush selection of the final selector shown in Fig. 6. After this has taken place a second one of these keys will be operated for tens selection and as soon as this has been accomplished a third key will be operated for units selection.

As soon as units selection has taken place and the line to which the testing device is connected has been found in a non-busy condition, the testing circuit shown in Fig. 2 will automatically determine whether said line is one extending directly to a subscriber, or one extending to a private branch exchange, and in determining this will also automatically associate the proper rheostats and resistances with switch 220 to give proper regulated current flow for testing the adjustments of the line switch apparatus.

The action of the apparatus functioning to differentiate between the types of line switching circuits as outlined in the preceding paragraph will automatically move switch 220 from its normal position thus starting the test of the line switch apparatus. Each action thereafter will aid in the progress of the test, excepting in tests where observation requires a longer period of time than an automatic movement of the switch would allow.

A ballistic test of this same line may be made by restoring to normal a key for the line switch test and actuating a key for said ballistic test. After operation of the ballis-

tic test key, the test of both conductors and connected apparatus is automatically carried to completion as follows: first, to discharge the latent capacity of the line and responsive mechanism connected thereto, 70 next, to test one conductor, the condition of which will be shown by the deflection of the voltmeter needle. The conductors of the line are then reversed with relation to the testing apparatus, and any latent capacity 75 in the conductors, and responsive mechanism is discharged. A ballistic test is then made of the other conductor, the condition of which may be noted by the deflection of the voltmeter needle. When this has been accomplished the switch will stop and restore the apparatus to normal, thus completing the ballistic test.

When the ballistic test is completed and the key for this test is restored to normal, 85 an insulation breakdown test may be made on the same line by the operation of a special key which will cause switch 400 to automatically make one rotation, discharging any latent capacity on the line. Switch 400 90 in restoring to normal will give impetus to switch 520, causing the potentiometer to be connected to the line in such a manner that an insulation breakdown test will be made on one conductor of the line without actuating the responsive mechanism connected thereto. As switch 520 returns to normal the potentiometer will function for discharging any latent capacity on the line and responsive mechanism connected thereto, 95 preceding the insulation breakdown test of another conductor of the line. This is accomplished when switch 520 restores to normal, actuating relays for the reversal of the line with relation to the testing circuit. The 100 apparatus functioning to reverse the line will automatically cause a second rotation of switch 520 to perform the insulation breakdown test of the other conductor of the line.

In the routine testing of the line switch 110 apparatus and lines of a machine switching office, the usual practice is to connect the testing circuit to the first line of a group or plurality of lines. When a test of this line has been completed the final selector is 115 caused to step to the next line above in the same group of lines. In this manner the final selector shown on Fig. 6 is caused to step from line to line until all the lines in that group have been tested, thus making it 120 unnecessary to restore the final selector after each test. The stepping of the final selector from terminal to terminal is accomplished by the operation of a single key which in turn causes the functioning of relays to accomplish the above-mentioned setting of the selector thus saving considerable time in the routine testing of the lines and line switches in an office.

The ability to test successively the con- 130

ductors of a line with automatically progressive apparatus is considered a time saving and accurate device. This favorable time factor is quite a consideration in the 5 cost of maintenance of the lines in a telephone office.

The tests outlined in the foregoing general description, i. e., line switch test, ballistic test and insulation breakdown test may 10 all be made upon a single connection to a line or any one of these tests may be made upon a connection to a line.

Having now given in general the utilities 15 of the testing circuit it is thought that the invention will be better understood from a consideration of the following detailed description.

Detailed description of operation.

20 The testing operator before proceeding with the first test ascertains by observation that the test selector, Fig. 6, is not busy, i. e., not being used in regular service, then proceeds by connecting the testing device, Figs. 25 1, 2, 3, 4 and 5, into operative relation with the final selector Fig. 6, by inserting the plugs of patching cord 325 into jacks 320 and 332, also the plugs of patching cord 326 into jacks 321 and 333. This final selector 30 is thereafter used as a part of the testing device to test lines within its scope of service. Patching cord 325 being inserted in jacks 320 and 332 connects ground to conductor 680 to make the test selector, busy to 35 other selectors in regular service. This busy ground may be traced from the left-hand inner contacts of key 131, sleeve of jack 320, patching cord 325 sleeve of jack 332 and conductor 671 to conductor 680.

40 Let it be assumed that the testing operator desires to test the line and apparatus connected thereto of the subscriber whose station is indicated at K. It will be assumed that this subscriber's number is 5322. Since 45 the final selector has immediate access to the line terminals, it is not necessary to consider the first or thousands digit (5). The other numerals must control final brush, final tens and final units selections. To connect the testing mechanism into operative 50 relation with the line above selected for test, the operator first actuates key 123, which is the No. 3 key. A circuit is thereupon established from ground through the left-hand outer contacts of key 131, left inner contacts of key 130, left contacts of key 123, winding of relay 146 to grounded battery, operating relay 146. The operation of relay 55 146 establishes a circuit for operating relay 145 which may be traced from ground on the outer left hand alternate contact of relay 507, inner right-hand contacts of relay 146, winding of relay 145 to grounded battery. Relay 146 also establishes a path for the 60 fundamental circuit which may be traced 65

from ground through contact 150 of key 131, alternate contacts of counting relay 110, winding of stepping relay 140, resistance 70 150, right-hand normal contacts of relay 147, outer right-hand contacts of relay 146, outer right-hand normal contacts of relay 214, conductor 370, tip of jack 320, patching cord 325, and jack 332, conductor 670, upper left-hand contact of sequence switch spring 617, lower left-hand contact of sequence switch spring 602, lower left-hand contact of sequence switch spring 603, winding 75 of relay 618, upper right-hand contact of sequence switch spring 604 to grounded battery. Relays 618 and 140 are energized 80 in this circuit. Other active paths closed by the operation of relays 146 and 145, connect ground to counting relays 100—119 for operating and locking paths for said relays. These paths are obvious and will not be 85 traced.

The operation of relay 140 connects ground from its contacts through the normal contacts of relay 147, right-hand contact of key 123, normal contacts of relay 113, winding of relay 103 to grounded battery, operating relay 103. The contacts of relay 103 close an obvious locking path for itself, and an operating path for relay 113, which, however, is not effective until the shunt ground over the operating path of relay 103 is removed. The operation of relay 618 establishes a path for operating relay 621 which may be traced from ground on the upper left-hand contact of sequence switch spring 608, left-hand alternate contacts of relay 618, conductor 623, upper left-hand contact of sequence switch spring 607, conductor 622, winding of relay 621 to grounded battery. The operation of relay 621 establishes a circuit for actuating sequence switch magnet 600, which may be traced from ground through the right hand alternate contacts of relay 621 and lower left and right contacts of sequence switch spring 609, winding of sequence switch magnet 600 to grounded battery, moving the sequence switch from position 1 to position 2. As soon as sequence switch 600 leaves position 1, the initial energizing circuit for relay 618 is opened at the lower left-hand contact of sequence switch spring 603, but relay 618 remains energized over the fundamental circuit through a locking branch of said fundamental circuit which may be traced from grounded battery through the upper right-hand contact of sequence switch spring 604, winding of relay 618, lower right-hand contact of sequence switch spring 610, right-hand alternate contact of relay 618, lower right-hand contact of sequence switch spring 603, lower left-hand contact of sequence switch spring 602, and thence over the fundamental circuit as previously traced. Be 100 105 110 115 120 125 130

fore reaching position 2 a circuit is established for energizing up drive magnet 626 which may be traced from grounded battery through the winding of magnet 626, upper right-hand contact of sequence switch spring 611, alternate contacts of relay 618, upper left-hand contact of sequence switch spring 608, to ground. Magnet 626 upon energizing causes the upward movement of the brushes of the switch in the manner well known in the art.

During the upward movement of the brushes of the selector switch, ground potential is intermittently connected to the fundamental circuit at a junction point between the winding of the stepping relay 140, and the winding of line relay 618. This ground potential is connected to the junction point at upper right hand sequence switch spring 602, through brush selection segment 630, brush 632, and upper left-hand contact of sequence switch spring 606, to ground. The application of this intermittent ground potential to the fundamental circuit has no resultant effect upon relay 618, but causes the intermittent deenergization of stepping relay 140 in synchronism with the upward movement of the brushes of the selector. As previously traced, counting relay 103 operated upon energization of relay 140, closes the operating path for relay 113 which operates upon the first deenergization of stepping relay 140. Upon the second energization of relay 140 a circuit is established for operating counting relay 102 extending from ground through contacts of relay 140, left-hand outer normal contacts of relay 147, contacts of key 123, alternate contacts of relay 113, normal contact of relay 112, winding of counting relay 102 to grounded battery. Counting relay 102 upon energizing closes a locking circuit for itself, extending through the winding of upper counting relay 112, and an operating circuit for relay 112 effective upon the second deenergization of stepping relay 140. Upon the third energization of stepping relay 140 over the fundamental circuit, a path is extended for operating counting relay 101 in the same manner as described for counting relay 102, and relay 111 in turn operates over the obvious path to contacts of relay 101 upon the subsequent deenergization of relay 140; and in this same manner the fourth energization of relay 140 establishes a path for operating counting relay 100, and the fourth deenergization of stepping relay 140 allows the operating path for relay 110 to become effective whereupon relay 110 energizes, opening the fundamental circuit at its normal contacts which opens the holding path for relay 618 causing it to be deenergized. Relay 618 upon deenergizing opens the previously traced circuit

through the up-drive magnet 626 to arrest the upward movement of the brushes. At its left-hand armature and back contact relay 618 closes a circuit extending from grounded battery through the magnet winding of sequence switch 600, upper right-hand contact of sequence switch spring 612 contacts of relay 618 to ground on upper left-hand contact of sequence switch spring 608 for driving sequence switch 600 out of position 2 and into position 3. Upon reaching position 3 sequence switch 600 closes a circuit for the trip magnet 635 extending from grounded battery through the winding of magnet 635 and thence to ground through the lower right-hand contact of sequence switch spring 606. Trip magnet 635 upon energizing rotates the tripping spindle (not shown) in the manner well known, into such a position as will trip the selected set of brushes upon the subsequent upward movement of the switch shaft.

Upon the operation of relay 110, as previously traced, a circuit is established for operating relay 142 which may be traced from grounded battery through winding of relay 142, normal contacts of relay 141, alternate contacts of relay 110, contacts 150 of key 131 to ground. The operation of relay 142 closes a circuit for operating the key release magnet 132 extending from ground through contact of relay 142, normal contacts of relay 141, winding of key release magnet 132 to grounded battery causing the contacts of key 123 to be opened which in turn opens the energizing path for relay 146 which releases. The release of relay 146 in turn opens the energizing path for relay 145 which releases removing the locking circuit for the counting relays extending through the contacts of relays 145 and 146 to ground thus releasing the counting relays which up to this time had remained locked. Upon the release of counting relay 110 ground is removed from the energizing path of relay 142, it, however, remains locked over a path which may be traced from grounded battery through winding of relay 142, left-hand contact of relay 142, winding of relay 141, contacts 150 of key 131 to ground operating relay 141, the utility of which will be described after unit selections have been completed.

Brush selection having been completed, the testing operator will actuate key 122 (the #2 key) to cause unit selection to take place. Relays 146 and 145 will be operated from the actuation of key 122 over the same paths as were traced upon the actuation of key 123, with the exception that the left-hand contact of key 122 is used instead of key 123. The circuit paths resultant from the operation of relays 146 and 145 are the same as previously described. Since the fundamental circuit is again closed by the

release of relay 110, and operation of relay 146, and since sequence switch 600 is in position 3 relay 618 and stepping relay 140 are again energized over a circuit extending 5 from grounded battery through upper right-hand contact of sequence switch spring 604, winding of relay 618, lower left-hand contact of sequence switch spring 603, lower left-hand contact of sequence switch spring 10 602, upper left-hand contact of sequence switch spring 617, tip of jack 332, patching cord 325 and jack 320, conductor 370, outer right-hand contact of relay 214, outer right-hand contact of relay 146, right normal contact of relay 147, resistance 150, stepping relay 140, normal contact of relay 110, contacts 150 of key 131 to ground, operating 15 relays 140 and 618.

Relay 618 when operated closes a circuit 20 for driving sequence switch 600 out of position 3 and into position 4, said circuit extending over a path including grounded battery, magnet winding of sequence switch 600, lower right-hand contacts of sequence switch 25 spring 612, left-hand contacts of relay 618 to ground at upper left-hand contact of sequence switch spring 608. Relay 618 in operating also closes the locking circuit previously traced for holding itself energized 30 over the fundamental circuit after sequence switch 600 leaves position 3. With sequence switch 600 in position 4 and relay 618 energized the circuit previously traced through the up-drive magnet 626 is again closed and 35 the brushes of the switch are again driven upwardly. During the initial upward movement of the brushes, the 4th set of brushes is tripped by tripping spindle in a manner well known, and during the subsequent upward movement of the switch shaft the tripped set of brushes travel in engagement with the terminals of the bank with which they are associated. During the upward movement of the switch shaft an intermittent 40 ground is connected to the junction point at lower left-hand sequence switch spring 602 over the circuit previously traced with the exception that the intermittent ground is derived from a circuit which may 45 be traced from this contact through upper right-hand sequence switch spring 603, conductor 636, tens selecting segment 637, brush 50 638 to ground at upper left-hand contact of sequence switch spring 606.

55 The energization of the stepping relay 140 with sequence switch 600 in positions 3 and 4 closes a circuit through the winding of counting relay 102 which may be traced from grounded battery through winding of 60 relay 102, normal contact of relay 112, right-hand contacts of key 122, outer left-hand normal contact of relay 147, contacts of relay 140 to ground. Counting relay 102 energizes in this circuit and locks in the manner previously described through the wind-

ing of counting relay 112 which circuit is effective for energizing relay 112 upon the first deenergization of stepping relay 140.

As brush 638 progresses in its upward movement connecting ground intermittently 70 to the energizing circuit for relay 140, the counting relays 101, 111, 100, and 110 are successively energized in the well known manner of operating counting relays as previously described. When counting relay 75 110 is energized on the third deenergization of stepping relay 140, or at the time the tripped set of brushes have been positioned on the first set of terminals of the group selected, the fundamental circuit is opened and relay 618 is deenergized, arresting the upward movement of the brushes and establishing a circuit for driving sequence switch 80 600 out of position 4 and into position 5. This circuit may be traced from grounded battery through sequence switch magnet winding 600, upper right-hand contact of sequence switch spring 612, normal contacts of relay 618 to ground on upper left-hand contact of sequence switch spring 608.

The energization of counting relay 110 establishes a circuit for operating relay 144 over a path extending from grounded battery through the winding of relay 144, 85 normal contact of relay 148, inner alternate contact of relay 141, alternate contact of relay 110, contacts 150 of key 131 to ground. Relay 144 closes a locking path for itself and an operating path for relay 143 which is effective upon the removal of shunt ground over the path traced for operating relay 144. The energization of relay 144 establishes a circuit for operating relay 200 which may be traced from grounded battery through left-hand normal contacts of relay 205, winding of relay 200, extreme right-hand contacts of relay 145 to ground through extreme right-hand contacts of relay 144. It also establishes a path for operating the key release magnet 132 which may be traced from grounded battery through key release magnet 132, right-hand alternate contacts of relay 141, left-hand normal contact of relay 143, to ground on right middle contacts of relay 144. Relay 200 operated from the aforesaid path established by relay 144 connected grounded battery through the right-hand winding of relay 211 to ground over the path for operating relay 200. The functions of relay 211 will be described after unit selection. The actuation of key release magnet 132 causes the release of key 122 which in turn opens the locking circuit for the counting relays by releasing relays 145 and 146. The release of counting relay 110 removes the shunt ground from the operating path for relay 143 which operates. This operation may be traced as follows: Grounded battery through winding of relay 144, right- 90 95 100 105 110 115 120 125 130

hand inner contact of relay 144, winding of relay 143, contacts 150 of key 131 to ground. The utility of relay 143 will be described after unit selection.

- 5 For units selection the testing operator will actuate key 122, (the No. 2 key) which will reoperate relays 146 and 145 in the manner described for brush selection. Relays 200 and 211 released upon the deenergization of relay 145. They will, however, again be operated at this time over the previously traced paths. The remaining contacts of relays 145 and 146 establish the same paths as described upon the operation 10 for tens selection, the same key being actuated. Since sequence switch 600 is in position 5, and since the fundamental circuit has again been established by the release of counting relay 110, and the operation of relay 146, as previously traced, relay 618 and stepping relay 140 will again be operated over the path previously described. Relay 618 in attracting its left-hand armature establishes a path for moving sequence switch 15 600 out of position 5 and into position 6 which may be traced from grounded battery through the sequence switch magnet winding 600, lower right-hand contact of sequence switch spring 612, contacts of relay 20 618, to ground on upper left-hand sequence switch contact 608. Relay 618 is again held over its locking path as previously traced. When sequence switch 600 reaches position 30 6 a circuit is closed for the slow speed up-drive magnet 639, over a path which may be traced from grounded battery through winding of slow speed up-drive magnet 639, lower left-hand contact of sequence switch spring 607, left-hand alternate contacts of relay 618, to ground on upper left-hand sequence switch spring 618. The brushes will again be driven in their upward movement. The fundamental circuit being closed in positions 5 and 6 of sequence switch 600, causing 35 the operation of relay 140, a path is established for the operation of counting relay 102 which may be traced from ground on contacts of relay 140, left-hand normal contacts of relay 147, right-hand springs of key 122, normal contact of relay 112, winding of relay 102, to grounded battery. The operation of relay 102 establishes a locking path for itself and prepares an operating 40 path for relay 112 in the well known manner of operating counting relays.

- The brush 632 is propelled upward by intermittently connecting ground to the commutator segment 630, conductor 629, upper right-hand contact of sequence switch spring 602, lower right-hand contact of sequence switch spring 603, contacts of relay 618, lower right-hand contact of sequence switch spring 610, and thence over the fundamental circuit as previously traced through upper right-hand contact of sequence switch spring

617. The intermittent ground will cause stepping relay 140 to energize and deenergize, in turn causing the operation of counting relays 102, 112, 101, 111, 100 and 110. The operation of relay 110 opens the fundamental circuit, causes the release of relay 618 which in turn arrests the upward movement of the selector brushes by opening the energizing path for up-drive magnet 639. Since the path for moving sequence switch 600 out of position 6 is open at jack 332, the sequence switch 600 will remain in position 6 until patching cord 325 is removed from jack 332. The operation of relay 110 establishes a path for the operation of relays 205 and 501 which may be traced from ground through contacts 150 of key 131, contacts of counting relay 110, alternate contacts of relay 141, alternate contacts of relay 143 and thence over a divided path, one path leading to the contacts and windings of relay 205 to grounded battery operating relay 205, the other path extending through the winding of relay 501 to grounded battery operating relay 501. Relay 205 locks over a path extending through its right-hand outer contacts, right-hand contacts of key 130, left-hand contacts of key 131 to ground. The operation of relay 205 removes the energizing path from relay 200 which releases in turn removing battery from the holding circuit of relay 211.

The operation of the final selector shown in Fig. 6 is otherwise the same as that disclosed and described in the previously mentioned application, Serial No. 487,520.

Assuming that line 5322 is a regular subscriber's station, (not extended to a private branch exchange), and again assuming that this subscriber's line is in a non-busy condition, there will not be a battery potential connected to conductor 280 and therefore relay 211 will be released.

A busy subscriber's line is characterized by the presence of battery on terminal 643. This battery is connected to terminal 643 from sequence switch spring 604 of a selector switch the same as that shown in Fig. 6, or from the source connected to arc 723 of line switch 705. Upon connection of the test final selector to the line terminals this battery may be traced from terminal 643 through brush 642, sleeve of jack 333, sleeve of patching cord 326, sleeve of jack 321, conductor 280, contacts and winding of relay 211, contacts of relays 145 and 144 to ground.

Relay 211 upon releasing establishes a circuit from grounded battery through right inner contacts of relay 205, winding of relay 206, winding of relay 207, terminal No. 1 of switch 222, brush 261, left inner contacts of key 241, left and right contacts of relay 301, right-hand contacts of key 241, left-hand normal contacts of relay 211, conductor

280, sleeve of jack 321, patching cord 326, sleeve of jack 333, brush 642, terminal 643, line switch brush 710 and its normal contact, lower and upper winding of relay 702, 5 to ground, operating relays 207 and 702. Marginal relay 206 does not, however, operate in this circuit because the resistance of relay 702 is too high to give the proper current value for operating said relay. Its operation will be brought into the description 10 under test of a line extending to a private branch exchange. The release of relay 211 also established a circuit for lighting lamp 234 which may be traced from ground 15 through resistance 257, lamp 234, right-hand normal contacts of relay 211, left-hand contacts of relay 205, to grounded battery. The lighting of lamp 234 indicated to the test man that line 5322 chosen for test is not 20 busy and therefore the test may proceed.

Assuming that the line switch apparatus is to be tested, key 245 is actuated by the testing operator. The actuation of key 245 establishes a circuit for the operation of 25 relay 212 which may be traced from grounded battery through windings of relay 212, left-hand outer contact of key 245, terminal 1 of arc 223, brush 262, to ground.

The operation of relay 207 establishes a 30 path for operating relay 214 which may be traced from grounded battery through winding of relay 214, right-hand contact of relay 207, right-hand contact of key 130, left-hand contact of key 131 to ground.

35 The combined operations of relays 212 and 207 establish a path for actuating switch magnet 220 from grounded battery through winding of switch magnet 220, contacts of magnet 220, brush 263, terminal 1 of arc 224, left-hand alternate contacts of relay 207, right-hand alternate contacts of relay 212 to ground, causing it to advance the brushes controlled by it into engagement with their second contacts. When the 40 switch moves from terminal 1 to terminal 2, the operating path for relay 702 is opened, causing the release of this relay. A path is, however, established for the non-operate 45 test of the cut-off relay 702 as follows:

50 A path is first established for the operation of relay 201 from grounded battery through winding of relay 201, terminal 2 of switch 223, brush 262 to ground. The operation of relay 201 establishes a path for connecting the non-operate current value to cut-off relay 702, which may be traced from 55 grounded battery, through resistance 362, rheostat 354, left-hand normal contacts of relay 204, winding of relay 202, right-hand inner contacts of relay 201, terminal 2 of arc 222, brush 261, left-hand inner contacts of key 241, contacts of relay 301, right-hand contacts of key 241, left-hand normal contacts of relay 211, conductor 280, sleeve of 60 jack 321, patching cord 326, and jack 333,

brush 642, terminal 643, conductor 722, brush 710, terminal 1 of arc 723, conductors 785, 715 and 764, lower and upper winding of cut-off relay 702 to ground.

In this test the current flow is held accurately correct by adjusting rheostat 35 to add a given amount of resistance in the circuit traced according to the voltage of the battery at the time of test.

The circuit traced for the non-operate 75 test of the cut-off relay 702 includes in its path a circuit for operating relay 202. The operation of relay 202 causes lamp 230 to be lighted over an obvious path and also establishes an obvious path for the operation of 80 relay 208. The lighting of lamp 230 indicates that the non-operate test of cut-off relay 702 is being made. When the switch controlled by magnet 220 moves from terminal 1 to terminal 2 the operating path for 85 relay 207 was opened, causing its release. Therefore, the operation of relay 208 will establish a path for actuating the switch magnet 220 from grounded battery through magnet 220, contacts of magnet 220, brush 263, terminal 2 of arc 224, right-hand contacts of key 340, right-hand alternate contacts of relay 208, right-hand outer contacts of relay 201, outer left-hand normal contacts of relay 207, right-hand alternate 95 contacts of relay 212 to ground, thus actuating switch magnet 220 and causing it to step from terminal 2 to terminal 3 under the control of its self-interrupting contacts.

90 It will be apparent from the following, that if relay 702 operates in the above test, the circuit path for operating relay 701 is opened. The progress of this test is then blocked with a signal lighted to indicate 100 the trouble.

An operate test of line relay 701 is made 105 with switch 220 in position 3. In making this test the non-operate test is continued on cut-off relay 702 for a check on the non-operate test and for the purpose of testing 110 pressure on the contacts through which the conductors for operating line relay 701 are carried. The path for continuing the non-operate test of the cut-off relay 702 is the same as previously traced with the exception that terminal 3 of arc 222 is used instead of terminal 2. The path established for making the operate test of line relay 701 may be traced from grounded battery through right-hand winding of line relay 115 701, lower alternate contacts of cut-off relay 702, conductor 703, terminal 657, brush 653, ring of jack 333, patching cord 326, and jack 321, left-hand contacts of relay 214, left-hand inner contacts of key 245, contacts of relay 300, brush 264, terminal 3 of arc 225, left-hand winding of induction coil 366, resistance 359, rheostat 351, terminal 3 of arc 226, brush 265, inner right-hand contacts of key 245, right-hand inner contacts 120 125 130

of relay 214, tip of jack 321, patching cord 326, jack 333, brush 652, terminal 659, conductor 704, upper normal contacts of cut-off relay 702 to ground. The operation of line relay 701 actuates switch magnet 705 from grounded battery through winding of switch magnet 705, contacts of magnet 705, conductor 706, lower normal contacts of cut-off relay 702, right-hand alternate contacts of line relay 701, conductor 707, brush 708 and the No. 1 terminal of arc 754, to ground. The line switch now rotates under the control of its self-interrupted contacts until a non-grounded terminal on arc 754 is encountered. The non-grounded condition of the terminal on arc 754 indicates that the corresponding trunk leading to a district selector is idle. When switch 705 stops in its forward movement it is connected to a district selector diagrammatically shown. This district being idle and thus in position 1, grounded battery will be connected to the terminal of arc 754 thus connecting this grounded battery to brush 708, conductor 707, left-hand contacts of line relay 701, left winding of line relay 701, conductors 786, 715 and 764, lower and upper windings of cut-off relay 702 to ground, operating relay 702. The operation of relay 702 establishes a path for the operation of relay 742 which may be traced from grounded battery through winding of relay 742, conductor 719, sequence switch spring 757, conductor 718, brush 709, terminal of arc 755, conductor 720, lower middle contacts of cut-off relay 702, conductor 780, upper winding of relay 702 to ground. The function of relay 742 is to actuate the apparatus in the district selector to cause it to hunt and find an idle sender, shown diagrammatically in lower right hand portion of Fig. 7, as described in the previously mentioned application, Serial No. 487,520, filed July 25, 1921. The detailed operation of this portion of the circuit will therefore not be described in this application. When an idle sender has been found dial tone is induced through the winding of relay 746 and is thus carried over lead 753, sender selector brush 743, upper left-hand contacts of sequence switch spring 760, conductor 717, brush 713 of arc 700, upper alternate contacts of cut-off relay 702, terminal 659, conductor 704, brush 752, tip of jack 333, patching cord 326, and jack 321, inner right-hand contacts of relay 214, inner right-hand spring of key 245, condenser 371, rheostat 351 and resistance 359, left-hand winding of induction coil 366, arc 225, brush 264, contacts of relay 300, left inner contacts of key 245, left-hand contacts of relay 214, ring conductor of jack 321, patching cord 326, jack 333, brush 653, terminal 657, conductor 703, lower inner alternate contacts of relay 702, brush 711 arc 756, conductor 716, lower left-hand contacts of se-

quence switch 761, sender selector brush 744, winding of relay 747 to battery. This induced dial tone through the left-hand winding of induction coil 366 is again induced on to the right-hand winding of induction coil 366 in turn being transmitted to receiver 338 over the obvious path closed by plug 337 being inserted in jack 335 and plug 336 being inserted in jack 334. This tone being transmitted to the test operator indicates the following:

- A. That the cut-off relay 702 did not operate with the proper non-operate current impressed upon its winding.
- B. That the line relay 701 operated with a current impressed upon its winding of such value that its operating adjustment is tested.
- C. That the line switch functioned properly to establish connection to a district selector.

D. That the cut-off relay 702 then operated properly.

E. That the district selector put into operation a sender selector to seize an idle sender.

F. That the seized sender transmitted dialing tone back to the testing apparatus.

With the line switch shown in the left-hand portion of Fig. 7, in its operated position, grounded battery is connected through a resistance to arc 723, brush 710, over conductor 722, terminal 643, brush 642, sleeve of jack 333, patching cord 326 and jack 321, thence over contacts of relay 211, right-hand contact of key 241, contacts of relay 301, left-hand contacts of key 241, brush 261, terminals of arc 222, right-hand contacts of relay 201, winding of relay 202, left-hand normal contacts of relay 204, rheostat 354, resistance 362 to grounded battery, thus causing relay 202 to release which in turn causes the release of relay 208, closing the path for actuating switch magnet 220. This may be traced from winding of magnet 220, contacts of magnet 220, brush 263, terminal 3 of arc 224, left-hand contacts of key 341, right-hand normal contacts of relay 208, right-hand outside contacts of relay 201, left-hand contacts of relay 207, right-hand alternate contacts of relay 212 to ground. The actuation of switch magnet 220 causes the switch to advance to position 4 under the control of the self-interrupting contacts of magnet 220.

In position 4 of the progression switch a test is made to ascertain whether resistance 727 is of the proper value to indicate a busy line switch of the type used for connection to a subscriber's station. Leaks, shorts or crosses are also indicated in this test. Lamp 232 is lighted to indicate to the testing operator that the progression switch 220 is in the proper position to make this test. The path for lighting lamp 232 may be traced from grounded battery through

resistance 250, lamp 232, left-hand inner normal contacts of relay 207, arc 223, brush 262 to ground. The tone also continues to be impressed upon induction coil 266 to indicate that the line switch 705 has remained in the proper position for this test. To make the ohmic resistance test of resistance 727 the operator will first actuate keys 241 and 340. Relay 301 is operated over an obvious path to ground on key 341. Ammeter 302 is actuated in series with resistance 727 which path may be traced as follows: grounded battery, through resistance 727, arc 723, brush 710, conductor 722, terminal 643, brush 642, sleeve of jack 333, patching cord 326 and jack 321 over conductor 280 through normal contacts of relay 211, right-hand outside contacts of key 241, right-hand contacts of relay 301, ammeter 302, left-hand contacts of relay 301, left-hand outer contacts of key 241 to ground. The deflection of the needle of ammeter 302 will indicate to the test man whether resistance 727 is of the proper value.

The next test of the line switch apparatus is a non-operated test of the line relay 701. This is accomplished by releasing keys 340 and 241 and operating key 243 which establishes a path for operating relay 207 which may be traced from grounded battery through right-hand inner contacts of relay 205, winding of relay 206, winding of relay 207, resistance 253, contacts of key 243, terminal 4 of arc 223, brush 262 to ground. Resistance 253 is sufficiently high to prevent the operation of relay 206. The operation of relay 207 extinguishes lamp 232 and in attracting its outer left-hand armature connects ground from the contacts of relay 212 through outer left-hand contacts of relay 207, terminal 4 of arc 224, brush 263, contacts of switch magnet 220, winding of switch magnet 220 to grounded battery actuating the switch magnet under the control of its self-interrupted contacts and causing it to rotate to terminal No. 7. Key 243 is thereupon released, and as will be noted, the operating circuit for relay 207 was opened at arc 223 when brush 262 stepped from terminal 6 to terminal 7.

Upon leaving terminal No. 4 the line circuit is opened at arc 226 causing the release of the district selector in the well-known manner. The release of the district selector opens the holding circuit of cut-off relay 702. The release of line relay 702 establishes a path for switch magnet 705 to rotate the line switch to normal under the control of its self-interrupted contacts. This path may be traced from grounded battery through switch magnet 705, contacts of switch magnet 705, conductor 706, lower normal contacts of relay 702, right-hand normal contacts of line relay 701, brush 712 to ground on arc 724. The switch 705 is

arrested in its rotary movement upon leaving the grounded portion of arc 724.

The release of the line switch apparatus as described above brings about the proper condition for making a non-operate test of the line relay 701. This test is accomplished in positions 7 and 8, of the testing device progression switch.

With line switch 705 in its normal position, a circuit is established for operating relay 202 which may be traced from grounded battery through resistance 362, rheostat 354, inner left-hand normal contacts of relay 204, winding of relay 202, right-hand inside contacts of relay 201, terminal 7 of arc 222, brush 261, left-hand inner contacts of key 241, contacts of relay 301, right-hand contacts of key 241, normal contacts of relay 211, conductor 280, sleeve of jack 321, patching cord 326, jack 333, brush 642, terminal 643, conductor 722, brush 710, conductors 785, 715 and 764, lower and upper windings of relay 702 to ground. Relay 702 is not operated in this circuit. The operation of relay 202 establishes an obvious path for operating relay 208, which by attracting its right-hand armature, establishes a path for rotating switch 220 into position 8. This path may be traced from battery through switch magnet 220, contacts of switch magnet 220, brush 263, terminal 7 of switch 224, right-hand contacts of key 340, alternate contacts of relay 208, outer right-hand contacts of relay 201, outer normal contacts of relay 207, right-hand contacts of relay 212 to ground.

In position 8 lamp 233 is lighted to show the testing operator that switch 220 has arrived in position 8. The path for lighting lamp 233 may be traced from grounded battery through resistance 250, lamp 233, left-hand contacts of relay 208, terminal 8 of arc 223, brush 262 to ground. The arrival of switch 220 in position 8 indicates to the testing operator that the line switch apparatus shown in Fig. 7 has restored to normal. The non-operate test of line relay 701 is now made. This is accomplished by a bridge across the tip and ring conductors of the line, including a rheostat previously accurately adjusted. The circuit of relay 701 may be traced as follows: grounded battery through right-hand winding of line relay 701, lower inner normal contacts of cut-off relay 702, conductor 703, terminal 657, brush 653, ring of jack 333, patching cord 226 and jack 321, left-hand contacts of relay 214, left-hand inner contacts of key 245, contacts of relay 300, brush 264, terminal 8 of arc 225, left-hand winding of induction coil 366, resistance 358, rheostat 350, terminal 8 of arc 226, brush 265, right-hand inner contacts of key 245, right-hand inner contacts of relay 214, tip of jack 321, patching cord 326 and jack 333, brush 652, terminal 139.

659, conductor 904, upper normal contacts of cut-off relay 702 to ground. Should the line relay 701 operate on the non-operate current value through its winding, the line 5 switch will again rotate to an idle district, in turn finding an idle sender as previously described. A sender found by the district will connect dial tone to coil 366, which will in turn be inducted through the windings 10 of coil 366 to the receiver 338 over the path described for the operate test of the line relay.

The non-operate test of the line relay 701 having been successful, an operate test may now be made of the cut-off relay 702. This is accomplished by operating key No. 244 to advance switch 220 from position 8 to position 9. The path for this advancement may be traced as follows: grounded battery 20 through winding of switch magnet 220, contacts of key 244, terminal 8 of arc 223, brush 262 to ground. The arrival of switch 220 in position 9 is indicated by the lighting of lamp 237 over an obvious path from 25 ground on brush 262 and terminal 9 of arc 223.

The operating path for the test of the cut-off relay 702 may be traced from ground through the upper and lower windings of 30 cut-off relay 702, conductors 764, 715 and 785, terminal 1 of arc 723, brush 710, conductor 722, terminal 643, brush 642, sleeve of jack 333, patching cord 326 and jack 321, left-hand normal contacts of relay 211, 35 right-hand contacts of key 241, contacts of relay 301, left-hand contacts of key 241, brush 261, terminal 9 of arc 222, normal contacts of key 242, normal right-hand contacts of relay 204, rheostat 357, resistance 365 to grounded battery. During this test the meter 450 is connected to the tip and ring of the line switch circuit to indicate by a deflection of the needle, a ground or 40 battery potential on these conductors. This ground and battery potential would be connected to the tip and ring leads if cut-off relay 702 failed to operate when the current value for its operate test is carried through its windings as above described. The path 45 for deflecting the needle of the meter may be traced from ground through normal contacts of relay 702, conductor 704, terminal 659, brush 652, tip of jack 333, patching cord 326, jack 321, right-hand inner contacts of relay 214, right-hand inner contacts of key 245, brush 265, terminal 9 of switch 226, resistance 254 to a junction point, which is also connected to the ring conductor, traced from grounded battery 50 through right-hand winding of line relay 701, lower normal contacts of cut-off relay 702, conductor 703, terminal 657, brush 653, ring of jack 333, patching cord 326, jack 321, left-hand contacts of relay 214, left inner contacts of key 245, contacts of relay 55

300, brush 264, terminal 9 of arc 225, resistance 255, to the junction point traced from the tip conductor. From this junction point a path may be traced through contacts 535 of key 530, winding of meter 450, resistance 432, right-hand outer normal contacts of relay 506, jack 323, plug 328, to a 100 volt battery poled in the opposite direction to the battery connected to the winding of line relay 701. It must be assumed for 75 this test that plug 328 has been inserted in jack 323 by the testing operator.

A holding test is now made by the operating key 242, which reduces the current through the windings of cut-off relay 702 by 80 placing additional resistance in series with said winding. The path from cut-off relay 702 to key 242 is the same as previously traced for operating the relay and from this point is extended over the inside spring 85 of key 242 through the normal contacts of relay 203, rheostat 352, resistance 360 and resistance 364 to grounded battery. Since switch 220 has not changed position the meter 450 remains connected to the tip and 90 ring of the line switch and therefore will show a deflection of the needle should the cut-off relay 702 release while being connected to the holding current value.

It will be noted that relay 213 is bridged 95 across the tip and ring leads, previously traced. From the line switch connection, it will also be noted that under certain condition of test the sleeve lead connected to the line switch is not retained in a busy 100 condition to other selectors of the office. Therefore, should a connection be made by a second final selector to the line switch under test, during one of these unguarded 105 periods, the attempt to ring the subscriber will operate relay 213 which path may be traced from ringing current applied from an incoming selector of the type shown in the previously mentioned application, Serial No. 487,520, over the ring conductor of a 110 final selector similar to the one shown in Fig. 6, brush 653, ring of jack 333, patching cord 326, jack 321, left-hand contacts of relay 214, left-hand inner contacts of key 245, condenser 266, winding of relay 213, 115 right-hand contacts of key 245, right-hand inner contacts of relay 214, tip of jack 321, patching cord 326, and jack 333, brush 652 to ground over tip conductor of final and incoming selectors. Relay 213 locks to the 120 locking ground of relay 212 and connects this same ground to lamp 236 and resistance 256 to grounded battery, lighting lamp 236 as an indication to the testing operator that a service connection has been established to 125 the line switch under test.

This completes the test of the line switch serving directly a subscriber. To restore the circuit to normal the test man releases key 245 and operates key 131, releasing all ap- 130

paratus that is in an operated position. Switch 220 restores to normal over a path from grounded battery through its magnet winding, self-interrupting contact, terminals 9 and 10 of arc 221, brush 260 to ground on normal contact of relay 212, switch 220 coming to rest on terminal No. 11. Terminals 11 to 20 on arcs 222, 223, 224, 225 and 226 and terminals 11 to 22 on arc 221 are duplicates of terminals 1 to 10. This does not include the restoring to normal of the final selector Fig. 6 which will be hereinafter described.

15 *Test of line switch extending to private branch exchange.*

It will now be assumed that the line to which the testing device is connected is one extended to a private branch exchange.

20 Assuming now that line 5322 is a line extending to a private branch exchange, and again assuming that the final selector has been directed to line 5322 by the apparatus in Fig. 1, as heretofore described, the apparatus of Fig. 1 will be in an operated position with the exception of relays 147 and 140. Key 245 is again operated by the testing operator and relays 205 and 212 of Fig. 2 are again operated to bring the testing 25 circuit to a point where relay 211 is in a position to test the busy or non-busy condition of the line switch. Assuming, in this test, that the line is found in a non-busy condition, relay 211 will release causing 30 lamp 234 to be lighted over a path which may be traced from ground through resistance 257, lamp 234, normal contacts of relay 211, left-hand alternate contact of relay 205 to grounded battery. The illumination of lamp 234 will indicate to the test man the accessibility of the line switch to be tested.

Referring now to Fig. 7 it will be remembered that the apparatus of the line switch 45 serving a private branch exchange is connected in a different manner than the line switch serving directly a subscriber's station. Conductor 763 is connected to conductor 715 in place of conductor 764. Conductor 781 is connected to arc 723 and conductor 783 is open (not connected to arc 723).

The upper winding of relay 702 is of low 55 resistance and the lower winding is comparatively high. Therefore, when the testing circuit is connected to a line switch, whose line is connected to a private branch exchange, a circuit is established for operating relays 206 and 207. This path may be traced 60 from ground connected to winding of cut-off relay 702, through upper winding of relay 702, conductors 780, 763, 715 and 785, brush 710, conductor 722, terminal 643, brush 642, sleeve of jack 333, patching cord 326, jack 321, left-hand normal contact of relay 211, right-hand contact of relay 241, contacts of relay 301, left-hand contact of key 241, brush 261, terminal No. 2 of arc 222, inner right-hand contacts of relay 201, winding of relay 202, inner left-hand contacts of relay 204, rheostat 355, resistance 363, to grounded battery thus completing the non-operate test 65 to cut-off relay 702 and operating relay 202. Relay 202, in attracting its contacts operates

right-hand contacts of key 241, contacts of relay 301, left-hand contacts of key 241, brush 261, terminal 1 of arc 222, winding of relay 207, winding of relay 206, contacts of relay 205 to grounded battery. The operation 70 of marginal relay 206 establishes a circuit for operating relays 203 and 204, which may be traced from grounded battery through winding of relay 203, winding of relay 204, contact of relay 206 to ground. Relay 207, in attracting its right-hand contacts, establishes an obvious circuit for the operation of relay 214 and in attracting its outer left-hand contacts establishes a circuit for energizing switch magnet 220 which may be traced from grounded battery through winding of switch magnet, contacts of switch magnet, brush 263, terminal 1 of arc 224, contacts of relay 207, right-hand contacts of relay 212 to ground. Switch magnet 220, 80 in energizing, propels the switch to terminal No. 2, under the control of its self-interrupting contact. Relay 203 in operating establishes an obvious locking path for itself and relay 204. Relay 204 closes an obvious circuit path through its outer left-hand contact for lighting lamp 231 to indicate to the testing operator the progress of the test and that the cut-off relay 702 is properly connected as one associated with a line 85 extended to a private branch exchange. The left-hand inner alternate contacts of relay 204 transfer the sleeve circuit from rheostat 354 and resistance 362 to rheostats 355 and 363, the former being regulated to test the cut-off relay of a line switch extended directly to a subscriber and the latter being regulated to test a cut-off relay associated with a private branch exchange line. When 90 the progression switch leaves terminal No. 1, the circuit for relays 206 and 207 is opened causing their release. When the switch arrives at terminal No. 2, a circuit is established for operating relay 201 which may be traced from grounded battery through the winding of relay 201, terminal No. 2 of arc 223, brush 262 to ground. Relay 201, in attracting its left-hand contacts, closes a locking circuit for itself. The inner right-hand contacts of relay 201 establishes a circuit for actuating relay 202, traced from ground at cut-off relay 702, through upper winding of relay 702, conductors 780, 763, 715 and 785, brush 710, conductor 722, terminal 643, brush 642, sleeve of jack 333, patching cord 326, jack 321, left-hand normal contact of relay 211, right-hand contact of relay 241, contacts of relay 301, left-hand contact of key 241, brush 261, terminal No. 2 of arc 222, inner right-hand contacts of relay 201, winding of relay 202, inner left-hand contacts of relay 204, rheostat 355, resistance 363, to grounded battery thus completing the non-operate test 100 to cut-off relay 702 and operating relay 202. Relay 202, in attracting its contacts operates 105

100

110

115

120

125

130

relay 208 over an obvious path which need not be traced. The actuation of relay 208 establishes a circuit for moving switch 220 from terminal No. 2 to terminal No. 3, which 5 may be traced from grounded battery through the winding of switch magnet 220, contact of magnet 220, brush 263, terminal No. 2 of arc 224, contacts of key 340, contacts of relay 208, right-hand outer contacts of 10 relay 201, outer left-hand contacts of relay 207, contacts of relay 212 to ground.

In position 3 of switch 220, the test of line relay 701 is made in the same manner as described for the test of the line switch serving directly a subscriber's line. This test, 15 however, in this case, is made in connection with the non-operate test of cut-off relay 702, as described above, regulated for a non-operate test when the line switch is connected to a private branch exchange. The operate test 20 of line relay 701 being successful, line switch 705 is rotated to find an idle district and sender which in turn induce tone into receiver 338, as previously described. The rotation of line switch 705 also connects battery in place of ground to the circuit of relay 202, causing it to be deenergized. The release of relay 202 will in turn release relay 208, the latter relay establishing a circuit for 25 moving switch 220 into position 4. This circuit may be traced from grounded battery through switch magnet 220, contact of magnet 220, brush 263, terminal 3 of arc 224, contacts of key 341, right-hand normal contacts of relay 208, right-hand outer contacts of relay 201, outer left-hand contacts of relay 207, right-hand contacts of relay 212 to ground.

In position 4 of switch 220, lamp 232 is 40 lighted to show the progress of the test and the successful operation and dismissal of the preceding test. This path may be traced from grounded battery through resistance 250, lamp 232, inner left-hand contacts of 45 relay 207, terminal 4 of arc 223, brush 262 to ground. In position 4, the ohmic resistance of line switch resistances 726 and 727 is measured by the operation of key 241 and key 340. The operation of key 340 50 establishes an obvious circuit for operating relay 301 which connects ammeter 302 in the sleeve circuit. The deflection of the ammeter needle will indicate to the testing operator the ohmic resistance value of resistances 55 726 and 727. This circuit may be traced from grounded battery through resistances 727 and 726, conductor 781, arc 723, brush 710, conductor 722, terminal 643, brush 642, sleeve of jack 333, patching cord 326, jack 321, left-hand normal contacts of relay 211, right-hand contacts of key 241, right-hand contacts of relay 301, ammeter 302, left-hand contacts of relay 301, outer left-hand contacts of key 241 to ground. Keys 241 60 and 340 are then released.

It will be remembered that the progression switch upon leaving position 4 opens the line conductors causing the release of the district selector. The release of the district selector opens the circuit of cut-off relay 702 70 thus establishing a path to restore the line switch to normal.

The next progressive test is the non-operate test of line relay 701. This is made in 75 the same manner as described for the test of the line relay in a line switch extending directly to a subscriber's station, after which the progression switch is moved into position 9.

In position 9 of switch 220, the operating 80 test of cut-off relay 702 is made with rheostat 356 adjusted in such a manner as to give proper current flow for testing the operating adjustment of relay 702 through its upper winding only. This operating 85 path may be traced from ground through the upper winding of cut-off relay 702, conductors 780, 763, 715 and 785, brush 710, conductor 722, terminal 643, brush 642, sleeve of jack 333, patching cord 326 and 90 jack 321, left-hand normal contacts of relay 211, right-hand contacts of key 241, contacts of relay 301, left-hand contacts of key 241, brush 261, terminal 9 of switch 222, contacts of key 242, right-hand alternate contacts of relay 204, rheostat 356, resistance 364 to grounded battery. In this operate 95 test of the cut-off relay, the voltmeter 450 is connected to the tip and ring of the line in the same manner as was done for the operate test of a cut-off relay of a line switch associated with a direct line. Therefore, this voltmeter will show a deflection should the cut-off relay 702 fail to operate from the current applied to its upper winding.

The operate test of the cut-off relay being the last test of the line switch apparatus extending to a private branch exchange, the testing operator will restore switch 220 to 100 normal by releasing key 245.

All paths established through the contacts of relays 300 and 301 may be carried 105 through milliammeter 302 by the operation of keys 341 and 340 which establish obvious operating paths on said relay. This accomplishes accurate regulation of adjustment current flow values.

Ballistic test of line.

Since the test circuit is connected to line 120 5322, a ballistic test of said line will be made. This is accomplished by operating key 442, which established a path for operating relays 422 and 423 which may be traced from grounded battery through left-hand alternate contacts of relay 205, right-hand normal contact of relay 211, right-hand outer contacts of key 245, winding of relay 423, winding of relay 422, contact 474 125 of key 422, left-hand outer normal contact 130

of relay 426, terminal No. 1 of arc 402, brush 408, terminal No. 1 of arc 525, brush 514, outer right-hand contact of relay 504 to ground. The operation of relay 423 establishes a circuit for lamp 461 which may be traced from ground through left-hand inner contact of relay 423, left-hand outer normal contact of relay 506, through lamp 461, resistance 430 to grounded battery, lighting lamp 461 to indicate to the testing operator that the test is in progress. The left-hand middle contact of relay 423 establishes a circuit for operating and releasing polarized relay 424 from alternating current which path may be traced from the alternating current on contact 471 of key 442, right-hand inner normal contact of relay 420, winding of relay 424, left-hand middle contact of relay 423, left-hand normal contact of relay 425, contact 470 of key 442 to ground. This polarized relay will operate on one side of the alternating current wave and will be released by the opposite side of the alternating current wave. As a result, relay 424 pulsates in synchronism with the current changes and causes switch 400 to rotate at the correct speed for properly discharging the latent capacity of the line and subscriber's set apparatus or apparatus of the private branch exchange. The rotation of switch 400 is accomplished as follows: A circuit is established for energizing relay 421 and switch 400 which may be traced from ground, through right-hand outer contact of relay 420, contact of relay 424, right-hand normal contact of relay 509, brush 409, terminal No. 1 of arc 403, over a divided path, one branch being directed through the magnet winding of switch 400 to grounded battery, and the other branch through the contact of switch 400, winding of relay 421 to grounded battery. Relay 421 being more rapid in its operation than switch 400, will be the first to operate to connect the second ground to the switch magnet 400, which may be traced from ground through outer left-hand contact of relay 423, brush 410, terminal No. 1 of arc 404, left-hand outer normal contact of relay 420, contact of relay 421, winding of switch magnet 400 to battery. The function of this secondary relay 421 is to introduce a lag in the releasing of ground from the switch magnet so that part of the released time of relay 424 can be used for the energizing of the magnet of switch 400. This switch is quick releasing when the ground is removed, as is well known in the art.

During the rotation of the switch from terminal No. 1 to terminal No. 10, inclusive, ground through coils of high ohmic resistance is connected to the tip and ring conductors of the line to discharge the static potential, termed latent capacity, that is present in the line or responsive apparatus con-

nected thereto. This ground connection may be traced from ground through resistance 436, terminals No. 1 to 10 of arc 406, brush 412, left-hand inner normal contacts of relay 505, left-hand inner contacts of key 245, left-hand contact of relay 214, ring of jack 321, patching cord 326 and jack 333, brush 653, terminal 657 to ring conductor and apparatus connected to the ring conductor of the line, also from ground through resistance 435, terminal 1 to 10 of arc 405, brush 411, outer left-hand contact of relay 505, inner right-hand contacts of key 245, inner right-hand contact of relay 214, tip of jack 321, patching cord 326, and jack 333, brush 652, terminal 659 to the tip conductor of the line and apparatus connected thereto.

The time allowed for the rotation of the switch is of sufficient duration to slowly discharge the latent capacity through resistances 435 and 436 to ground. The value of these resistances is sufficiently high to prevent actuation of the responsive apparatus connected to the line.

When switch 400 reaches terminal 11, the line has, therefore, been completely discharged of latent capacity so that when the testing battery is connected thereto, the ringer magnet in the subscriber's station or responsive apparatus, depending upon the type of line service, will not be energized by a discharge from said capacity. In a subscriber's station such discharge of capacity might cause the energization of the ringer magnet which would in turn cause the attraction of the ringer magnet armature to which the bell clapper is connected. This would cause the subscriber to remove the receiver from the switchhook, thus causing inconvenience to the subscriber and interference with the test.

As switch 400 moves into position 12, ground is connected to the ring side of the line and 100 volt test battery is connected to the tip side of the line through meter 450. This connection to the line may be traced as follows: ground is connected through contacts of key 444, left-hand normal contacts of relay 428, terminals 12 to 21 of arc 406, brush 412, left-hand inner contacts of relay 505, left-hand inner contacts of key 245, left-hand contacts of relay 214, to the ring of the line through final selector, Fig. 6, as heretofore traced. The 100 volt test battery 390 is connected through plug 328 which is inserted in jack 323, outer right-hand contact of relay 506, through windings 432, 433, 434 of meter 450, right-hand normal contact of relay 428, terminals 12 to 21 of arc 405, brush 411, left-hand normal contacts of relay 505, right-hand inner contacts of key 245, right-hand inner contacts of relay 214 and thence over the tip of the line through the final selector as heretofore traced. As the brushes 411 and

412 rotate over terminals 12 to 21 of arcs 405 and 406, the connection just traced will cause a ballistic movement of the voltmeter needle if the line is free from ground or battery or short circuits.

A ballistic movement of the voltmeter needle is easily distinguished from the needle deflection for other causes by one skilled in testing.

10 It will be remembered that counting relays and other relays in Fig. 1 remained locked after units selection.

15 During the progress of switch 400 from terminals 3 to 8, a circuit is established for operating relay 507 which may be traced from grounded battery through the winding of relay 507, terminals 3 to 8 of arc 402, brush 408, terminal 1 of arc 525, brush 514, right hand outer contacts of relay 504 to ground. The operation of relay 507 removes the operating path from relay 145 causing its release, which in turn removes the locking paths for the counting relays 100 to 119, causing those that are operated to release.

20 Upon leaving terminal 8 of switch 400, the operating circuit of relay 507 will be opened, thus causing its release and the reactivation of relay 145 over the previously traced path. When switch 400

25 arrived at terminal No. 12, a circuit is established for the operation of relay 425 which may be traced from grounded battery through the winding of relay 425, terminals 12 to 21 of arc 402, brush 408, terminal 1 of arc 525, brush 514, right hand normal contacts of relay 504 to ground. Relay 425 in attracting its left hand contacts opens the operating circuit for relay 424.

30 In attracting its inner right-hand contacts counting relay No. 102 is actuated from ground through interrupter 392, plug 329 inserted in jack 324, left-hand outer contacts of relay 501, right-hand inner contacts of relay 425, winding of counting relay 102 to grounded

35 battery. Counting relays 112, 101, 111, 100 and 110 will be operated in the manner of operating counting relays as previously outlined in this description. During the time that the counting relays are progressing in their operation from interrupter 392, switch

40 400 is arrested in its movement to allow a delayed time interval for reading the deflection of the needle in meter 450. Relay 110 in attracting its contacts establishes a circuit

45 for operating relay 501 which may be traced from ground through the contacts of key 131, contacts of counting relay 110, right-hand inner contacts of relay 141, right-hand contacts of relay 143, winding of relay 501 to grounded battery.

50 Relay 501 in attracting its left-hand inner contacts reestablishes the operating circuit of polarized relay 424. This circuit may be traced from ground through contacts of relay 501, left-hand contacts of relay 425, left-hand middle contacts

of relay 423, winding of relay 424, right-hand inner contacts of relay 420, contacts 471 of key 442, to alternating current connected to that contact. The reestablishment of the actuating path for relay 424 will again rotate switch 400 under the control of the contacts of relay 424, in combination with relay 421, as previously described. Lamp 463 is lighted upon the operation of relay 525 to display the fact that the ring side of the line is being tested. This circuit may be traced from grounded battery through resistance 431, lamp 463, right-hand inner normal contacts of relay 426, outer right-hand contact of relay 426, left-hand outer contacts of relay 425, left-hand normal contacts of relay 506, left-hand inner contacts of relay 423 to ground.

55 When switch 400 reaches terminal 22, a circuit is established for operating relay 426 which may be traced from grounded battery to winding of relay 426, left-hand normal contact of relay 427, terminal 22 of arc 404, brush 410, left-hand outer contact of relay 423 to ground. Relay 426 establishes a locking circuit for itself, which may be traced from grounded battery through winding of relay 426, winding of relay 427, winding of relay 428, outer right-hand contacts of relay 426, right-hand inner contacts of relay 503, contact 472 of key 442, right-hand inner contact of relay 504, left-hand contact of relay 422, contacts of key 443, to ground. Also, in attracting its left-hand inner contacts, ground is connected to the switch magnet 100 winding 400, which may be traced from ground through left-hand inner contacts of relay 426, left-hand outer contacts of relay 504, right-hand contacts of relay 427, brush 407, terminal 22 of switch 401, contact of switch magnet 400, winding of magnet 400 to grounded battery rotating switch 400 from terminal 22 to terminal 1.

60 It will be noted that when switch 400 is resting on terminal 22, the shunt ground is connected to conductor 480 to prevent relays 427 and 428 from operating. This shunt path may be traced from ground through left-hand outer terminals of relay 423, brush 410, terminal 22, left-hand normal contact of relay 427, to conductor 480. Therefore, when switch 400 rotated from terminal 22 to terminal 1, this shunt path is removed and relays 427 and 428 are operated over the locking path for relay 426, previously traced. The operation of relay 426, in attracting its right-hand inner contacts, extinguished lamp 463. Relay 428, in operating, transfers the ground connection from the ring of the line to the tip of the line and the voltmeter from the tip of the line to the ring of the line. Relay 427 transfers the control leads, which will be described hereinafter.

65 Relay 425 released when switch 400 130

stepped to terminal 22, therefore upon stepping to terminal #1 the originally traced circuit for pulsating relay 424 is continued and switch 400 is again rotated in a manner 5 described for the initial rotation, again discharging any capacity existing in the line or responsive mechanism connected thereto. Upon reaching terminal 12 the line has been discharged and the tip side of the line will 10 be tested. At this time the testing circuit may be traced from ground through contacts of key 444, right-hand contacts of relay 428, terminals 12 to 21 of arc 405, brush 411, outer left-hand normal contacts of relay 505, inner right-hand contacts of key 245, inner right-hand contacts of relay 214 and thence to tip of line through the final selector, Fig. 6, as previously traced. Testing battery 390 is connected through plug 20 328, jack 323, outer right-hand normal contact of relay 506, resistance 432 meter 450 in parallel with resistances 433, 434, left-hand contacts of relay 428, terminals 12 to 21 of arc 406, brush 412, left-hand inner 25 normal contacts of relay 505, left-hand inner contacts of key 245, left-hand contacts of relay 214 and thence to the ring side of line through the final selector shown in Fig. 6. This will cause the ballistic movement of voltmeter needle if the line is free from ground or battery or short-circuits.

Relay 507 is operated during the progression of the switch, over the previously described path. The operation of relay 507 again opens the operating path of relay 425 releasing any counting relay that may be operated. During the movement of switch 402 through terminals 12 to 21, relay 425 is operated from grounded battery through 30 the winding of relay 425, terminals 12 to 21 of arc 402, brush 408, terminal No. 1 of switch 525, brush 514, right-hand outer normal contacts of relay 504 to ground. In attracting its right-hand outer contacts, a circuit is established for lamp 460 to indicate 35 that a ballistic test is being made on the tip side of the line. This circuit may be traced from grounded battery through resistance 250, lamp 460, right-hand inner contact of relay 426, right-hand outer contact of relay 425, left-hand outer normal contact of relay 506, left-hand inner contacts of relay 423 to ground. The remaining contacts attracted by this actuation of relay 425 function to bring about the delay for accurate 40 reading of the voltmeter needle deflection as described under the test of the ring conductor. When switch 400 completes the ballistic test of the tip side of the line and arrives at terminal 22, relay 420 is operated from grounded battery, through its winding, left-hand alternate contacts of relay 427, terminal 22 of arc 404, brush 410, outer left-hand alternate contacts of relay 423 to 45 ground. In attracting its inner left-hand

contact relay 420 closes a locking ground for itself which may be traced through said contact, left-hand outer contacts of key 441, left-hand outer contacts of key 440, contacts 476 of key 442, right-hand inner contact of relay 504, left-hand contact of relay 422, right-hand contacts of key 443 to ground. In attracting its inner right-hand contacts, the pulsating circuit for relay 424 is opened, thus preventing further movement of switch 50 400 from its pulsating circuit. In attracting its outer right-hand contacts, ground is connected to the winding of magnet 400 for moving it from terminal 22 to normal. This may be traced from ground through the outer right-hand alternate contacts of relay 420, right-hand contact of key 440, right-hand contacts of key 441, brush 407, terminal 22 of arc 401, contact of magnet 400, winding of switch magnet to grounded 55 battery.

If while the voltmeter test is being made, the testing operator observes a deflection of the voltmeter needle that might indicate to him that the line is connected to a foreign potential, grounded or short-circuited, he may determine the nature of the trouble by operating keys 440 or 441 depending upon the line conductor that is under test. If either of keys 440 or 441 are operated, switch 400 will stop in its progression and remain at that point until the key is restored. Assuming the trouble has appeared while the test is being made on the tip conductor, the actuation of key 440 will establish a circuit for operating relay 420, which may be traced from grounded battery through the winding of relay 420, left-hand inner contact of key 440, right-hand inner alternate contact of relay 426, right-hand outer contact of relay 425, outer left-hand normal contact of relay 506, left-hand inner contact of relay 423 to ground. The operation of relay 420 opens the operating path traced for relay 424, thus arresting the forward movement of switch 400. The remaining contacts of relay 420 are not effective at this time. The contacts of key 440, in addition to establishing an operating circuit for relay 420, opens ground paths which, if they remain in an established condition, would interfere with the proper functioning of the apparatus from a time margin standpoint only.

The testing operator makes particular note of the voltmeter needle deflection and in order to ascertain the trouble will operate key 444, removing the ground from the tip conductor so that the deflection of the voltmeter needle can indicate whether an extraneous ground or battery potential is connected to the line. After making the necessary observations the testing operator will restore key 440 to normal, which will, in turn, release relay 420, reestablishing the 120 125 130

circuit for continuing the rotation of switch 400. Key 441 may be operated in the same manner when the ring side of the line is being tested and a deflection of voltmeter 450, other than a ballistic deflection, is noted.

Insulation break-down test.

The line ballistic test having been completed, the next test to be made by the testing operator is an insulation break-down test. This is accomplished by operating key 530 and releasing key 442, which in turn releases relay 420. Relays 422 and 423 will remain operated or will be re-operated, depending upon the sequence with which these keys are operated and released. The path for re-operating relays 422 and 423 extends upwardly to contacts 537 of key 530, terminal 1 of arc 521, brush 510 to ground. Relays 424 and 421 will also function for rotating switch 400, the source of alternating current and ground, however, for pulsing relay 424 being from contacts 538 and 539 respectively, of key 530. A circuit is established for operating relay 506 traced from grounded battery through winding of relay 506, contact 531 of key 530, contact 475 of key 442, right-hand contact of relay 422, left-hand contact of key 443 to ground. The operation of relay 506 establishes an obvious path for operating relay 504.

Switch 400 is caused to rotate in a manner similar to that previously described for the ballistic test, this rotation however, being to discharge capacity of the line, including the responsive apparatus connected thereto, before starting an insulation break-down test so that actuation of said responsive apparatus will not take place when the potential for the insulation break-down test is connected to the line.

The operation of relay 504 establishes a circuit for operating relay 505 which may be traced from grounded battery through winding of relay 505, left-hand inner contact of relay 504, terminals 10 and 11 of arc 402, brush 408, when that brush is rotated to the position of terminals 10 and 11, terminal 1 of arc 523, brush 512, right-hand outer contact of relay 504 to ground. There is not any effective operation when switch 400 is rotating from terminal 11 to 22.

When switch 400 arrives at terminal 22, a circuit is established for operating relays 503 and 509, which may be traced from grounded battery through the winding of relay 503, winding of relay 509, right-hand contact of relay 505, terminal 22 of arc 402, brush 408, terminal 1 of arc 523, brush 512, right-hand outer contact of relay 504 to ground. The locking path is established for relays 503 and 509 from grounded battery through their windings over left-hand inner contact of relay 509, contact 531 of key 530,

left-hand contact of relay 422, right-hand contacts of key 443 to ground. Also, in position 22 of switch 400, a circuit is established for operating relay 426, traced from grounded battery, through winding of relay 426, left-hand normal contacts of relay 427, terminal 22 of arc 404, brush 410, left-hand outer contact of relay 423 to ground. The operation of relay 426 establishes a circuit for operating relay 420 traced from grounded battery through winding of relay 420, right-hand outer contact of relay 503, left-hand outer contact of relay 504, left-hand contact of relay 426 to ground. The operation of relay 420 establishes a circuit for stepping switch 400 to normal which may be traced from grounded battery through magnet winding of switch 400, contact of magnet 400, terminal 22 of arc 401, brush 407, right-hand contact of keys 441 and 440, right-hand outer contact of relay 420 to ground. Upon the stepping of switch 400 to normal the actuating paths of relays 420 and 426 are opened. These relays are therefore released. Relay 505 in attracting its left-hand inner and outer contacts transfers the line conductors from arcs 405 and 406 to ground and a potentiometer connected to the terminals of switch 526, ground being connected to the ring, and the potentiometer being connected to the tip as may be readily understood from the previous description.

The potentiometer is arranged to connect the insulation break-down voltage to the line conductor without causing actuation of the responsive mechanism connected thereto. Ground is connected from the right-hand normal contact of relay 502 to terminal 1 and terminal 22 of the potentiometer switch 526 with resistance of the proper value, connected to the intermediate terminals to vary the voltage in even steps from zero to maximum and from maximum again to zero. The middle terminal of the switch is connected through the meter 450 to the insulation break-down battery 390 and 391, poled in opposite to the central office battery. Therefore as switch 526 rotates, the tip conductor of the line being connected to brush 515, the resistance between the ground and the tip conductor is continuously increased and the resistance between the insulation break-down battery and the tip conductor is decreased until the central point of switch 526 is reached where the movement of switch 526 is arrested for direct application of the insulation break-down potential and reading of the voltmeter. The process of increasing the resistance between the insulation break-down battery and the tip of the line will then take place until terminal 22 is reached where ground is again connected to the tip of the line. The meter 450 is constantly under observation of the testing operator during the time that this switch

is rotated. This rotation is accomplished in detail as follows:

The initial impetus was given to switch 520 when the operation of relay 509 established a circuit from grounded battery through the magnet winding 520, contacts of magnet 520, brush 513, terminal 1 of arc 524, right-hand inner contacts of relay 509, left-hand contacts of relay 508 to ground. Thereafter switch 520 is rotated under the control of relay 424 and relay 510. Relay 424 being intermittently operated by alternating current as previously described establishes an operating circuit for relay 510, which may be traced from ground through right-hand outer normal contacts of relay 420, contacts of relay 424, outer right-hand alternate contacts of relay 509, brush 511, terminals 2 to 9 and 11 to 21 of switch 522, contacts of switch magnet 520, winding of relay 510 to grounded battery. Therefore ground is connected from two sources to the switch magnet 520, one source being as just traced from the operating path of relay 510 and another source which may be traced from ground through the right-hand alternate contacts of relay 504, brush 512, terminals 2 to 9 and 11 to 21 of switch 523, contacts of relay 510, switch magnet 520 to grounded battery. Relay 510 is used in conjunction with 424 to allow an added period of time for operating switch 520 in each of its steps. As is well known in the art, the stepping switch of this type is very quick in releasing, the release causing it to step to the next terminal. When switch 520 is rotating from terminal 2 to terminal 7, a circuit is established for operating relay 507 which may be traced from grounded battery through winding of relay 507, terminals 2 to 7 of arc 521, brush 590, to ground. Relay 507 in attracting its left-hand outer contacts, removes ground from the locking circuit for relay 145, releasing relay 145, thus disconnecting ground from the locking circuit for counting relays 100 to 119, releasing such counting relays as were operated. The remaining contacts of relay 507 do not function at this time. Upon the arrival of switch 520 at terminal 11 the testing battery is connected directly to the line, as may be traced from the testing battery 390 and 391, through plug 327, inserted in jack 322, outer left-hand contacts of relay 509, contacts 534 of key 530, resistance 434, meter 450, contacts 535 of key 530, left-hand contacts of relay 503, terminal 11 of arc 526, brush 515, left-hand inner contacts of relay 500, left-hand inner contacts of relay 505, right-hand inner contacts of key 245, right-hand contacts of relay 214, tip of jack 321, patching cord 326, jack 333, brush 652, terminal 659, and thence to the line conductor and mechanism connected thereto. The ring of the line at this time is connected to

ground as previously traced. The indication of poor insulation may be observed at this time by the testing operator should the meter needle show unusual deflection.

When switch 520 steps from terminal 10 to terminal 11 the path for operating switch magnet 520 is opened at arcs 522 and 523 causing switch 520 to remain on terminal 11 until it is given impetus from a source other than relay 424, as described later. 75

With switch 520 in position 11 a circuit is established for the operation of relay 502 which may be traced from grounded battery through winding of relay 502, terminal 11 of arc 523, brush 512, right-hand outer contacts of relay 504 to ground. Relay 502 in attracting its right-hand contacts establishes a circuit for lighting lamp 463 to indicate to the testing operator that the ring conductor is being tested. This circuit may be traced from grounded battery through resistance 431, lamp 463, outer right-hand contacts of relay 508, right-hand contacts of relay 502 to ground. 80

The operation of relay 502 also removes ground at its right-hand alternate contact from the potentiometer. This ground is used as a means for graduating the voltage connected to the tip conductor of the line in approximately 20 volt steps solely to prevent the actuating of responsive mechanism connected to the line. With arc 526 in position 11 this ground is removed as a last step of graduation so that there will not be a shunt path for the testing battery and therefore the total insulation break-down potential will be applied at this time. 90

In order that the testing operator may have sufficient time for observation of the meter needle deflection, switch 520 is caused to stop on terminal 11 awaiting action of the counting relays operated from an interrupter, before rotating to terminal 12. The circuit for this time measuring device is established through the left-hand contacts of relay 502 which may be traced from ground connected to interrupter 392, plug 329 inserted in jack 324, left-hand outer normal contacts of relay 501, left-hand contacts of relay 502, right-hand contacts of relay 116, winding of relay 106 to battery. Since relay 507 released when switch 520 reached terminal 8, ground was again connected to the winding of relay 145 actuating it and reestablishing ground locking paths for the counting relays 101 to 119. Therefore as interrupter 392 rotates, reaching an insulated segment it removes the ground from the operating path of relay 106. The shunt will therefore be removed from the operating path of relay 116 thereby operating it in the well known manner of operating counting relays. The operation of relay 116 connects the interrupter circuit to an operating path for relay 105 which operates in a manner 110

described for operating relay 106 and thereafter relay 115 will operate when the interrupter 392 rotates to an insulated segment and in this manner the pairs of counting 5 relays will be consecutively operated by the rotation of interrupter 392. When relay 110 is operated a circuit is established for operating relay 501 which may be traced from grounded battery to winding of relay 10 501, right-hand normal contacts of relay 143, right-hand inner alternate contacts of relay 141, left-hand contacts of relay 110, right-hand contacts of key 131 to ground. Since these counting relays are not released 15 at this time, relay 501 remains operated. Relay 501 in attracting its right-hand contacts connects ground to the potentiometer resistances at terminal 1 and 22 of switch 526 and in attracting its left-hand inner 20 contacts, it establishes a circuit for rotating switch 520 from position 11 to position 12 which may be traced from ground through contacts of relay 501, terminal 11 of arc 524, brush 513, self-interrupting contacts of 25 switch 520, switch magnet winding 520 to grounded battery. The movement of switch 520 out of position 11 opens the operating path for relay 502 which releases, in turn reconnecting ground to the potentiometer 30 resistances effective for the second rotation of switch 520. In position 12 relay 507 is again operated from ground on brush 590 through winding of relay 507, to grounded battery, opening the energizing path for relay 145 releasing relay 145 and in turn releasing the counting relays 100 to 106 and 35 110 to 116, inclusive.

Switch 520 will now continue to rotate under the control of polarized relay 424, and 40 relay 510, as previously described, and in rotating will decrease the insulation breakdown battery potential with relation to the tip conductor of the line until ground is connected directly to that conductor at terminal 22 of arc 526. The movement of switch 45 520 will be arrested at terminal 22 since it will be noted that upon reaching this terminal the movement of the switch is no longer under the control of relays 424 and 510.

50 With switch 520 resting on terminal 22 a circuit is established for energizing relay 500 which may be traced from ground through brush 590, terminal 22 of arc 521, winding of relay 500 to grounded battery. Relay 500 in attracting its right-hand inner contacts closes a locking path for itself which may be traced from grounded battery through its winding and right-hand inner contacts, contacts 533 of key 530, right-hand 55 inner contacts of relay 422, left-hand contacts of key 443 to ground. Relay 500 in attracting its left-hand outer and inner contacts reverses the potentiometer and ground with relation to the conductors of the line, 60 and in attracting its outer right-hand con-

tacts establishes an energizing circuit for relay 507 which may be traced from ground through contacts of relay 500, winding of relay 507 to grounded battery. Since relay 500 will remain energized over the locking 70 path traced therefor, relay 507 will now remain energized. Relay 507 in attracting its inner left-hand contacts establishes a circuit for energizing switch magnet 520 which may be traced from ground through contacts of relay 507, terminal 22 of arc 524, brush 513, self-interrupting contact of magnet 520, winding of magnet 520 to grounded battery, thus causing the movement of switch 520 from terminal 22 to terminal 1. 80

The potentiometer in its progression from terminal 11 to terminal 22 discharged the capacity in the line and mechanism connected thereto. Therefore the insulation break-down test of the ring line conductor 85 may proceed automatically when switch 520 reaches terminal 1. Switch magnet 520 is energized over a circuit extending from ground through left-hand normal contacts of relay 508, inner right-hand contacts of relay 509, terminal 1 of arc 524, brush 513, self-interrupting contacts of switch magnet 520 to grounded battery. Upon reaching terminal 2 the progression of switch 520 is again under the control of polarized relay 90 424 and relay 510, gradually increasing the insulation break-down potential in steps of approximately 20 volts until terminal 11 is reached whereupon the insulation break-down potential is connected directly to the ring conductor of the line and ground is connected to the tip conductor of the line and a path for the insulation break-down potential is established through the meter as previously traced for the test of the opposite 105 conductor of the line.

With switch 520 in position #1 it is no longer under the control of relay 424 and is therefore arrested in its forward movement.

In this position a circuit is established 110 for the operation of relay 508 which may be traced from grounded battery through the right hand contacts of relay 507, winding of relay 508, terminal 11 of arc 521, brush 590 to ground. Relay 508 in attracting its left-hand contacts establishes an obvious locking path for itself and in attracting its right-hand inner contacts establishes a circuit for operating relay 145 which may be traced from ground on right-hand inner contacts of relay 508, left-hand outer contacts of relay 507, right-hand inner contacts of relay 146, winding of relay 145 to grounded battery. Brush 512 resting on terminal 11 of arc 523, establishes a 120 path for operating relay 502 which may be traced from grounded battery through winding of relay 502, terminal 11 of arc 523, brush 512, outer right-hand contacts of relay 504 to ground. Relay 502 in attract- 125 130

- ing its right hand contacts establishes a circuit for lighting lamp 460 which may be traced from ground to right-hand contacts of relay 502, outer right-hand contacts of relay 508, lamp 460, resistance 250 to grounded battery. This lamp indicates to the testing operator that the tip conductor of the line is being tested. The energization of relay 502 also establishes a circuit for the time measuring device incorporating the use of interrupter 392 with counting relays of Fig. 1, which may be traced from ground through interrupter 392, plug 329 inserted in jack 324, outer left-hand contacts of relay 501, left-hand contacts of relay 502, right-hand normal contacts of relay 116, winding of relay 106 to grounded battery. The counting relays will operate in rotation as previously described allowing a predetermined period of time for observation of the ammeter needle deflections by the testing operator when the insulation break-down potential is connected directly to the conductor of the line and responsive mechanism connected thereto.

Relay 110 having operated, will establish a circuit for actuating relay 501 in the same manner as previously traced for the actuation of the same relay. The operation of relay 501 reestablishes a circuit for connecting ground to the outer terminals of the potentiometer 541, 542. In attracting its left-hand inner contacts a circuit is established for moving switch 520 out of position 11 over its self-interrupting contacts which may be traced from grounded battery, through winding of switch magnet, self-interrupting contact of switch magnet 520, brush 513, terminal 11 of arc 524, contacts of relay 501 to ground.

When the switch 520 reaches terminal 12, it is again propelled under the control of relays 424 and 510 as previously described until it arrives at terminal 22 when it is removed from the control of these relays and arrested in its forward movement. A path is established for the movement of switch 520 from terminal 22 to terminal 1 which may be traced from grounded battery through winding of switch magnet 520, self-interrupting contact of magnet 520, brush 513, terminal 22 of arc 524, left-hand inner contact of relay 507 to ground and since the path for causing switch 520 to rotate from terminal No. 1 is now open at relay 508 the switch will remain in its normal position.

The insulation break-down test having been completed, the testing operator will restore key 530 and actuate key 443, thus releasing such relays as are still energized.

Progressive stepping to other lines.

The line switch apparatus and conductors of line No. 5322 including responsive

mechanism connected thereto, have now been tested. By means of a key in Fig. 1 the selector switch may be controlled to associate the testing circuit with the line appearing above line No. 5322 in the terminal bank without restoring to normal the final selector shown in Fig. 6 or again actuating the selective relays shown in Fig. 1. It will therefore be noted that the selector may be elevated in single steps to any line above the one on which its brushes are resting. 70

The actuation of key 130 will establish a path for operating relay 147 which may be traced from grounded battery through winding of relay 147, right-hand contacts of key 130, left-hand contacts of key 131 to ground. Relay 147 upon energization locks up through its inner left-hand alternate contact to ground at key 131. The actuation of key 130 also opens the holding circuit for relay 214 causing its release. The holding circuit for relays 146 and 145 is also opened upon the actuation of key 130 thus causing them to release in turn releasing counting relays that may have been operated by a previous function of the testing circuit. The release of counting relay 110 in turn establishes a path for the fundamental circuit. Key 130 is now restored to normal causing the reoperation of relays 145 and 146 over a path previously traced. The operation of relay 145 reestablishes the locking paths for the counting relays. The operation of relay 146 completes the closure of the fundamental circuit over its outer right-hand contacts.

A circuit is now established for the operation of relay 210 which may be traced from grounded battery shown in Fig. 6, through upper right-hand sequence switch spring 604, winding of line relay 618, upper right hand sequence switch spring 617 tip of jack 332, patching cord 325 and jack 320, conductor 370, right-hand normal outer contacts of relay 214, right-hand contacts of relay 146, right-hand alternate contacts of relay 147, right-hand normal contacts of relay 209, the middle and right-hand windings of relay 210, left-hand contacts of relay 146 to ground. Relay 210 is operated over the path traced but on account of the right-hand winding of relay 210 being of high ohmic resistance, line relay 618 does not operate over this path. The operation of relay 210, however, short circuits this high resistance winding by its right-hand contact and due to its elimination from the circuit path traced, relay 618 will operate. Relay 209 does not operate at this time. Relay 618 in attracting its right-hand contacts closes a locking circuit for itself which may be traced from ground through upper left-hand sequence switch springs 606 brush 632 which is resting on the metal segment of commutator 630, upper right-hand sequence 105 110 115 120 125 130

switch spring 602 lower right-hand sequence switch spring 603 right-hand contacts of relay 618, lower right-hand contact of sequence switch spring 610, winding of relay 618, upper right-hand sequence switch spring 604 to grounded battery. This ground is also carried through upper right-hand sequence switch spring 617 to tip of jack 332, patching cord 325, jack 321, outer right-hand contacts of relay 214, outer right-hand contacts of relay 146, right-hand alternate contacts of relay 147, right-hand normal contacts of relay 209, left-hand contacts of relay 210, left-hand winding of relay 210, winding of relay 209 to battery, operating relay 209 which locks relays 209 and 210 through its right-hand contacts, left-hand contacts of relay 146 to ground. In attracting its left-hand contacts relay 209 establishes a circuit from the winding of relay 618 through stepping relay 140 to ground which will be hereinafter traced. Relay 618 in attracting its left-hand armature establishes a path for energizing the updrive magnet 639 which may be traced from ground through upper left-hand sequence switch spring 608 left-hand alternate contacts of relay 618, lower left-hand sequence switch spring 607 winding of updrive magnet 639 to grounded battery, thus causing the elevation of the brushes over the commutator in the manner well known in the art. The brushes in their upward movement will pass from the metal segment of commutator 630 on to the insulated segment of said commutator, thus removing the ground traced to the fundamental circuit. Relay 618 will, however, remain locked over the fundamental circuit through the winding of stepping relay 140, operating said stepping relay over a path traced from grounded battery through upper right-hand contact of sequence switch spring 604, right-hand winding of relay 618, upper right-hand contacts of sequence switch spring 617, tip of jacks 332, patching cord 325, jack 320, right-hand outer contacts of relay 214, right-hand outer contacts of relay 146, right-hand alternate contacts of relay 147, left-hand contacts of relay 209, resistance 150, winding of stepping relay 140, normal contacts of relay 110, right-hand contacts of key 131 to ground. The operation of relay 140 connects ground through its contacts, left-hand alternate contacts of relay 147, winding of counting relay 100 to grounded battery, operating relay 100 which establishes a locking circuit for itself and an operating path through the winding of relay 110 which is effective upon release of the stepping relay. Brush 632 in its upward movement will pass from the insulated portion of the commutator 630 to the metal portion thus reconnecting ground from brush 632 to the fundamental circuit which continues to hold relay 618 over its locking path and releases stepping relay 140 in the well known manner of shunting stepping relays. The release of relay 140 will in turn remove the ground shunt from relay 110 causing it to operate. Relay 110 in attracting its contacts opens the fundamental circuit and therefore when brush 632 again passes from the metal segment of the commutator to the insulated segment of the commutator, the holding circuit for relay 618 will be removed, causing its release. The release of relay 618 opens at its left-hand contacts the energizing path for updrive magnet 639 and the elevator is therefore arrested in its movement causing brushes 652, 653 and 642 to come to rest on the line terminals next above the line to which it was connected on the preceding test. The brush does not remain upon the last mentioned insulated segment. Upon the release of the updrive magnet 639, the brushes engaging the terminals and commutator are brought to rest at a point below their location when the magnet is released as is well known in the art. This allows the commutator brush to engage a non-insulated segment when at rest. The feature of stepping the final selector shown in Fig. 6 to the next line above may be repeated as often as is necessary to test the lines of a given group, the connection being the same as in the foregoing description. It may also be stepped to a line several lines above without testing the intermediate lines by associating the stepping mechanism with a counting relay other than 100.

Ballistic test without other tests.

It may be desirable at times in the maintenance of a telephone exchange system to use this testing device for making a ballistic test on all the lines, without making the other tests incorporated in this device. Therefore, a feature has been incorporated in combination with the stepping of the final selector to the next line above, to start the ballistic test automatically, when that line is found free (not busy), independent of the release and reoperation of key 442.

As previously described, relays 422 and 423 remain locked, upon the completion of a ballistic test, over a path extended to battery on contacts of relay 208 through the contacts of relay 211. Therefore, when relay 211 is operated during the elevation of the final selector from one terminal to another the operating circuit for relays 422 and 423 is opened, and upon the seizure of that line, relay 211 is again released, reclosing the operating path for relays 422 and 423.

The release of relays 422 and 423 in turn causes the release of relays 426, 427 and 428 so that upon the release of relay 211 and

reoperation of relays 422 and 423 the apparatus of Fig. 4 will automatically be given impetus for making said ballistic test as previously described.

5 *Line seized by final in service*

When a busy line is encountered by the test circuit, including the final selector shown in Fig. 6, relay 211 will remain operated and establish a path for lighting lamp 235 from grounded battery on left-hand contacts of relay 205 over an obvious path which need not be traced. The path for holding relay 211 in an operative position 16 may be traced from ground through the left-hand outer contacts of relay 144, right-hand outer contacts of relay 145, left-hand winding of relay 211, left-hand contacts of relay 211, sleeve of jack 321, patching cord 326, 20 and jack 333, brush 642, terminal 643 and a multiple thereof to battery by way of the upper right-hand contacts of a sequence switch spring corresponding to 613, at a final selector circuit the same as that shown in 25 Fig. 6, except that it is one in regular service. A final selector in regular service that has seized a line will be in sequence switch position 11 or beyond.

It may be desirable to wait for this line to 30 become idle. Therefore the test circuit will be allowed to remain on the terminals of that line and the testing operator will await the lighting of lamp 234 which will indicate that the line to be tested has become free. This 35 lamp will be lighted upon the release of relay 211 which will occur when the final selector in regular service disconnected itself from said line.

Upon completion of all of the tests that 40 can be made by advancing the final selector in single steps from line, to line the final selector and testing circuit will be restored to normal by removing patching cords 325 and 326 from jacks 332, 320, 333 and 321. 45 Key 131 will also be actuated to release the apparatus of the testing circuit that is at that time held in an operated position over locking paths.

The removal of patching cord 325 from 50 jack 332 removes ground from conductor 671 allowing relay 621 to restore to normal. The contact of jack 332 will establish a circuit for energizing the sequence switch magnet winding which may be traced from grounded 55 battery through magnet winding 600, lower left contact for sequence switch 625 (6), contacts of jack 332, normal contacts of relay 618, upper left-hand contact of sequence switch spring 608, to ground rotating sequence switch 600 from position 6 into position 7. The release of relay 621 establishes a circuit from ground through its right-hand contact upper left and lower right contacts of sequence switch spring 609 winding of magnet 600 to grounded battery, causing se-

quence switch to move into position 13. In position 13 relay 621 is operated over a path from grounded battery through left-hand winding of relay 621, upper right-hand contact of sequence switch spring 603 to ground. In attracting its right-hand contacts ground is connected through the lower contacts of sequence switch spring 609 winding of magnet 600 to grounded battery, rotating sequence switch from position 13 into position 14.

In position 14 a circuit is established for the downdrive magnet 644 which may be traced from grounded battery through winding of magnet 644, lower right-hand contacts of sequence switch spring 611 lower right-hand contacts of sequence switch spring 615 upper right and left-hand contacts of sequence switch spring 609 to ground at the right-hand normal contacts of relay 621, which released when the sequence switch left position 13. The elevator of the selector will thus be restored to normal and upon reaching its normal position will establish a circuit for rotating the sequence switch 600 from positions 14 to 17 which path may be traced from ground through upper left-hand contact of sequence switch 606, conductor 633, brush 638, commutator segment 647, conductor 646, upper left-hand contact of sequence switch spring 612 winding of magnet 600 to grounded battery. Upon reaching position 17 a circuit will be established for rotating sequence switch 600 into position 18 from ground through right-hand normal contacts of relay 621, upper left and lower right-hand contacts of sequence switch spring 609 winding of magnet 600 to grounded battery. Upon reaching position 18, the switch will be restored to normal over a circuit established from ground through upper left-hand contacts of sequence switch spring 606, brush 638, commutator 647, upper left-hand contact of sequence switch spring 612, winding of magnet 600 to grounded battery.

All of the apparatus has now been restored to its normal condition and is ready for re-use.

What is claimed is:

1. In a telephone exchange system, a plurality of line switches, a testing device, an automatic switch associated with said testing device to select a desired one of said line switches, means in said testing device for conducting tests on said line switch, and signaling means responsive to said tests for denoting the success or failure of said tests.
2. In a telephone exchange system, a plurality of line switches, a testing device, a plurality of automatic switches to select line switches, means to associate said testing device successively with said automatic switches, and means in said testing device for conducting tests on said line switches.

3. In a telephone exchange system, a plurality of line switches, a testing device, a plurality of automatic switches to select line switches to be tested, means to associate said testing device successively with said automatic switches, means in said testing device for conducting a series of tests on each line switch, and signaling means responsive to said tests for denoting the success or failure 10 of said tests.
4. In a telephone exchange system, a plurality of line switches, automatic switches regularly used for completing service connections, a testing device, means to associate said testing device successively with said automatic switches, means to maintain an automatic switch thus associated busy to other switches in service, and means to direct said automatic switch to select a particular line switch to be tested.
5. In a telephone exchange system, a plurality of line switches, automatic switches regularly used for completing service connections, a testing device, means to associate said testing device successively with said automatic switches, means to maintain an automatic switch, thus associated busy to other switches in service, and means to direct said automatic switch to successively select line switches to be tested.
6. In a telephone exchange system, a plurality of line switches, automatic switches regularly used for completing service connections, a testing device, means to associate said testing device successively with said automatic switches, a sending device included in said testing device, and means to direct said automatic switches under the control of said sending device to select line switches to be tested.
7. In a telephone exchange system, a plurality of line switches, automatic switches regularly used for completing service connections, a testing device, means to associate said testing device successively with said automatic switches and means to direct said automatic switch by the revertive control method to select line switches to be tested.
8. In a telephone exchange system, a plurality of line switches, an automatic switch regularly used for completing service connections, a testing device, means to associate said testing device with said automatic switch, a circuit controlling switch associated with said selector switch, means to direct said automatic switch to select a line switch to be tested means to change the position of said circuit controlling switch as selections progress, means to test said line switch, and means to cause said automatic switch to select other line switches while said circuit controlling switch is resting in a selecting position.
9. In a telephone exchange system, a line, an automatic switch associated with said line, a testing device, means to establish a testing connection between said testing device and said line, means to conduct a series of tests on said automatic switch, means to establish a service connection to said line while said switch is under test, and means operative upon such connection to prevent interference by said testing device.
10. In a telephone exchange system, line switches for different types of service, a testing device for testing said line switches, means to determine the type of service rendered by a line switch and means to apply tests in accordance with such differentiation.
11. In a telephone exchange system, line switches for different types of service, a testing device for testing said line switches, and means in said testing device to determine the type of service rendered by a line switch under test.
12. In a telephone exchange system, line switches for different types of service, a testing device for testing said line switches, means to determine the type of service rendered by a line switch, means responsive to said means of differentiation to apply a series of tests on the line switch apparatus, and signaling means controlled by said tests to denote the success or failure of said tests.
13. In a telephone exchange system, different types of line switches, a testing device for testing said line switches, and means in said testing device to differentiate between said types of said line switches.
14. In a telephone exchange system, different types of line switches, a testing device for testing said line switches, means in said testing device to differentiate between said types of line switches, and means in said testing device for testing the adjustments of the apparatus in each of said different types of line switches.
15. In a telephone exchange system, different types of line switches, a testing device for testing said line switches, means in said testing device to differentiate between said types of line switches, means in said testing device responsive to said means of differentiation to test the adjustments of the apparatus of each of said different types of line switches and signaling means responsive to said tests to denote the success or failure of said tests.
16. In a telephone exchange system, a plurality of line switches, a testing device for testing said line switches, a selector switch, means for connecting said testing device with said selector switch, a sender at said testing device, and means to direct said selector switch to select a desired one of said line switches.
17. In a telephone exchange system, a plurality of line switches, a testing device to

test said line switches, a selector switch, a circuit controlling switch associated with said selector switch, means to connect said selector switch, a testing device with said selector switch, a sender at said testing device, means to operate said selector switch under the control of said sending device, means to change the position of said circuit controlling switch as selections progress, means to connect said selector switch with one of said line switches, and means to select a different line switch independent of position change of said circuit controlling switch.

18. In a telephone exchange system, a plurality of line switches, a testing device for testing said line switches, an automatic selector switch, means to connect said testing device with said automatic selector switch, means to control said automatic selector switch to associate a line switch with said testing device, means to prevent said automatic selector switch from releasing, means to control said automatic selector switch to successively associate a plurality of line switches with said testing device while said automatic selector switch is in a non-released condition.

19. In a telephone exchange system, a line switch, a testing device for testing said line switch, a selector switch, means for connecting said testing device with said selector switch, a sender to control said selector switch to establish a testing connection between said testing device and said line switch, means in said testing device to make a plurality of tests upon the apparatus of said line switch and a plurality of signals to indicate whether the apparatus of said line switch has properly responded to said tests.

20. In a telephone exchange system, a line switch, a testing device for testing said line switch, a selector switch, means for connecting said testing device with said selector switch, a sender to control said selector switch to establish a testing connection between said testing device and said line switch, means in said testing device to make a plurality of tests upon the circuits and apparatus of said line switch and a plurality of signals to indicate the condition of said circuits and apparatus.

21. In a telephone exchange system, an automatic switch, a testing device for testing said automatic switch, means in said testing device for making a plurality of tests upon the apparatus of said automatic switch, a plurality of signals for indicating whether the apparatus of said automatic switch has properly responded to the various tests, a tone used as a signal to indicate the success of a particular test, and means of receiving said tone in said testing device.

22. In a telephone exchange system, a line switch, a testing device for testing said line switch, a selector switch, means for connecting said testing device with said selector switch, a sender to control said selector switch to associate the testing device with said line switch, means in said testing device to make a plurality of tests upon the apparatus of said line switch, a plurality of signals for indicating whether the apparatus of said line switch has properly responded to the various tests, a tone used as a signal to indicate the success of a particular test, and means of receiving said tone in said testing device.

23. In a telephone exchange system, a line switch, a testing device for testing said line switch, means to associate said testing device with said line switch, means in said testing device for making a plurality of tests on the apparatus of said line switch, a plurality of service selector switches, and means whereby a particular one of said tests causes the line switch to select an idle selector switch as in service.

24. In a telephone exchange system, a line switch, a testing device for testing said line switch, means to associate said testing device with said line switch, means in said testing device for making a plurality of tests upon the apparatus of said line switch, a plurality of service selector switches, means whereby a particular one of said tests causes the line switch to select an idle selector switch as in service and a signal in said testing device controlled by the operation of said service selector switch.

25. In a telephone exchange system, a line switch, relays associated therewith, a testing device for testing said line switch, a source of current supply at said testing device, and means in said testing device for regulating the current flow when testing relays of said line switch.

26. In a telephone exchange system, a line switch, relays associated therewith, a testing device for testing said line switch, a source of current supply at said testing device means in said testing device for regulating the current flow for any test, means in said testing device to apply the non-operate test to a relay of said line switch with said regulated current flow and signaling means in said testing device to indicate the operation of said line switch relay when said non-operate test is applied to said line switch relay.

27. In a telephone exchange system, a line switch, relays associated therewith, a testing device for testing said line switch, a source of current supply at said testing device, means in said testing device for regulating current flow for any test, means in said testing device to apply the operate test

- to a relay of said line switch with said regulated current flow and signaling means in said testing device to indicate the action of said relay when said operate test is applied.
28. In a telephone exchange system, a line switch, a testing device for testing said line switch, a selector switch, means for connecting said testing device with said selector switch, means to control said selector switch to associate said line switch with said testing device, means in said testing device including a progression switch to make a plurality of tests upon said line switch, means responsive to a successful test to advance said progression switch into position for making the next successive test and signaling means operable at said position of test for indicating said position of test and for indicating the success of the preceding test.
29. In a telephone exchange system, a line switch, a testing device for testing said line switch, a selector switch, means for connecting said testing device with said selector switch, means to control said selector switch to associate said line switch with said testing device, means in said testing device including a progression switch to make a plurality of tests upon said line switch, means responsive to a successful test to advance said progression switch, and means to repeat said succession of test on said line switch.
30. In a telephone exchange system, a plurality of line switches, automatic switches regularly used for completing service connections, a testing device, means to associate said testing device with said automatic switches, means to direct said automatic switches to successive line switches to be tested, means to make a succession of tests on each line switch, and means to repeat said succession of tests on anyone of said line switches.
31. In a testing system for testing the operation of automatic line switches, an automatic selector switch temporarily removed from service to be used as part of said testing system, means for establishing operating conditions in a line switch, a recording device, and means controlled by said line switch in its operation for controlling said recording device.
32. An arrangement for testing telephone lines, comprising automatic testing means and a meter with a deflectable needle responsive to a plurality of different electrical conditions indicating by the deflection of said needle unstandard conditions in different parts of said lines, and means for automatically and successively associating said testing means and meter with the different parts of the line to be tested.
33. An arrangement for making ballistic tests on line conductors and electrically responsive apparatus connected thereto, comprising automatic testing means, and a meter responsive to a plurality of different electrical conditions indicating unstandard conditions in different parts of said lines, means for automatically and successively associating said testing means and meter with the different parts of the line to be tested, and means for discharging latent capacity to prevent actuation of said electrically responsive apparatus connected to said line conductors under test.
34. In a telephone exchange system, a plurality of lines, each line comprising a plurality of conductors connected to electrically responsive apparatus, a testing device for testing the conductors and responsive apparatus of said lines, automatic means in said testing device to make successively a plurality of ballistic tests on the conductors and responsive apparatus of each line in such manner that the responsive apparatus will not be actuated.
35. In a telephone exchange system, a line comprising a plurality of conductors connected to electrically responsive apparatus, a testing device for testing said lines, said device comprising automatic means to make successively a plurality of ballistic tests on the conductors and electrically responsive apparatus of said line, and means to discharge latent capacity preceding each of said succession of ballistic tests to prevent actuation of said electrically responsive apparatus during said ballistic tests.
36. In a telephone exchange system, a line to be tested, said line comprising a plurality of conductors connected to electrically responsive apparatus, a testing device for testing said line, a key, means operable from a single actuation of said key for making successively a plurality of ballistic tests on the conductors and responsive apparatus of said line, and means to prevent the actuation of said responsive apparatus during said ballistic tests.
37. In a telephone exchange system, a line to be tested, said line comprising a plurality of conductors connected to electrically responsive apparatus, a testing device for testing said line, automatic means for making successively a plurality of ballistic tests on the conductors and electrically responsive apparatus of said line, means to prevent the actuation of said responsive apparatus during said ballistic tests, and means for indicating any abnormal condition when making said ballistic tests.
38. In a telephone exchange system, a plurality of lines extending to subscriber's station apparatus, each line consisting of a plurality of conductors, a testing device for testing said conductors and subscriber's station apparatus including bells, said test-

ing device comprising means operable to make successively a plurality of ballistic tests on the conductors and substation apparatus of said lines independent of assistance at the subscriber's station and in such manner that the bell at the subscriber's station will not be sounded, and means to indicate any abnormal condition of said conductors or substation apparatus when making said ballistic tests.

39. In a telephone exchange system, a plurality of lines, each line comprising a plurality of conductors connected to electrically responsive apparatus at the distant end, a testing device for testing the conductors and responsive apparatus of said lines, a service selector switch, means for temporarily seizing said selector switch to be used as part of said testing device, a sender to control said combined testing device to select lines to be tested, automatic means for making successively a plurality of ballistic tests of said conductors and responsive apparatus of each of said lines independent of assistance from said distant end and in such manner that the responsive apparatus at the distant end will not be actuated.

40. In a telephone exchange system, a plurality of lines, each line comprising a plurality of conductors connected to electrically responsive apparatus at the distant end, a testing device for testing said lines, a selector switch, means for connecting said testing device with said selector switch, a sender at said testing device, means controlled by said sender for connecting said selector switch with any one of said lines, automatic means for making successively a plurality of ballistic tests on the different parts of one of said lines, means for discharging latent capacity in said line preceding each of said plurality of ballistic tests, means for holding said selector switch in a non-released condition, means in said testing device for elevating said non-released selector switch to the next succeeding line, means in said testing device independent of any manual action for making the same ballistic tests on said last connected line as on the preceding line.

41. In a telephone exchange system, a plurality of lines, electrically responsive apparatus connected to the conductors of each line, a testing device including automatic means for making an insulation break-down test successively on the different parts of said line.

42. In a telephone exchange system, a plurality of lines, electrically responsive apparatus connected to the conductors of each line, a testing device, means to operate said testing device to perform various tests on said lines and electrically responsive apparatus connected thereto, said tests including

an insulation break-down test applied in such manner that said responsive apparatus is not actuated, and a progression switch to control the sequence of said tests.

43. In a telephone exchange system, a plurality of lines, electrically responsive apparatus connected to each line, a testing device capable of making an insulation break-down test on said lines, said testing device including a potentiometer, and means for applying said potentiometer to make an insulation break-down test in such manner that said responsive apparatus will not be actuated.

44. In a testing system for testing telephone lines and electrically responsive apparatus connected thereto, a potentiometer, comprising a source of battery potential of a voltage for making an insulation break-down test, a device with a plurality of points of contact, a rotating member of said device, capable of contacting with said plurality of points of contact during rotation, means connected to said contacts of said device for changing the potential in graduated steps from ground to direct application of the insulation break-down potential and in graduated steps from direct application of the insulation break-down potential to ground, automatic means for making an insulation break-down test on the different parts of said line, with said potentiometer, in such manner that said electrically responsive apparatus will not be actuated, and means for automatically and successively associating said potentiometer with the different parts of said line to be tested.

45. A testing system, a line to be tested, a meter to indicate unstandard conditions in said line, means automatically progressive to test said line, and means to defer action of said automatic progression for a limited time to facilitate reading of said meter.

46. A testing system, a line to be tested, means automatically progressive to test said line, a meter, a needle in said meter to indicate the line conditions, and means automatically operated during said progressive tests to defer said progression for a limited time to facilitate reading the deflection of said meter needle.

47. An arrangement for testing telephone lines comprising, automatic testing means and a meter, responsive to a plurality of different electrical conditions indicating unstandard conditions in different parts of said lines, means for automatically and successively associating said testing means and meter with the different parts of the line to be tested, and means to automatically defer progression for a limited time interval, at various points of test, to facilitate the reading of said meter.

48. A testing system, a line to be tested, a

meter to indicate unstandard conditions in said line, means automatically progressive to test said line, means to defer action of said automatic progression to facilitate reading of meter, a set of counting relays, means to control said set of counting relays to operate in a given time period, and

means when the last of said series of counting relays has operated to continue said progression.

In witness whereof, I hereunto subscribe my name this 27 day of April A. D., 1923.

ERIC R. LUNDIUS.
